RAILWAY TRAIN OPERATING SYSTEM

Archibald G. Shaver, Chicago, Ill.

Application September 2, 1933, Serial No. 687,990

20 Claims. (Cl. 246—8)

This invention relates to railway train operating and dispatching systems and has special reference to the provision of improved means for communication on and with trains and between 5 wayside stations.

The apparatus and system herein disclosed are claimed broadly in my copending applications Serial No. 227,932, filed Oct. 22, 1927; Serial No. 304,483, filed Sept. 7, 1928; Serial No. 541,131, 10 filed May 30, 1931, and Serial No. 605,380, filed Apr. 15, 1932.

More specifically, the system disclosed provides means for communication between the conductor on the rear and the engineman on the 15 head of trains, between trains, between trains and local wayside stations, between the train dispatcher and either the conductor or the engineman or both, and between the dispatcher and local wayside stations, that information may be 20 had by each and instructions issued with regard to the operation of the railway, including the operating of trains into and out of passing sidings in meeting and passing other trains. Further, in connection with the means for communication, there are means for the operation of 25 the switches concerned for trains to enter and leave sidings and pass other trains. In these systems each train operates in a communication zone of its own which always includes an intermediate wayside circuit. The stretch of track 30 over which the trains operate is sectionalized into blocks and an intermediate circuit is provided for each block; but as, and during the interval in which the train travels from one 35 block to the next, the two intermediate circuits for the adjoining blocks are automatically connected together as one circuit, thus creating a traveling circuit effect, which, for convenience, is sometimes referred to as a traveling intermediate 40 circuit. The intermediate circuits are arranged so that there is always an intermediate circuit in continuous communicative relation with both ends of the train as the train travels through the corresponding block or blocks and each such circuit is also provided with means for communicative connection with the communication means 45 provided for the dispatcher and the local wayside stations.

The means used for communication between 50 rear end and head end of a train about to pass into, through or to leave a passing siding territory, are automatically connected with the dispatcher's communicating set, but the dispatcher may cancel such connection. Means are also 55 provided for persons in local wayside stations to

normally communicate with standing and moving trains within prescribed areas. The means referred to are under the control of the dispatcher to the extent that he may, at will, connect or disconnect the communication circuit connected with his communication set from any train or local wayside communication set.

One object of the invention is the provision of means for continuous communication between two communication stations on a train while 10 the train is passing between the main line track and the passing siding track, of a passing siding location, and yet, under normal conditions, communications passed between the two train stations, while the train is on the passing siding 15 track, are kept to the train.

Another object of the invention is the provision of means whereby, when desired, communication may be carried on between two points on the train, while the train is on the passing siding, 20 and yet, the train is normally not in communicating relation with another train on the main track adjoining the passing siding track.

Another object of the invention is the provision of means for establishing communication be- 25 tween a train on a siding track and a train on an adjoining main track.

Still another object of the invention is the provision of means for increasing the efficiency 30 of the system in the transfer of communication energy between the train and the wayside and between two points on a train.

Provision is made for communication to be carried on between two communication stations, 35 as two local roadside stations, simultaneously with communication being carried on between two or more stations, as between a train carried station and the dispatcher, neither set of communications interfering with the other. 40

Provision is also made for carrying on communication between two stations in the system with the transmitter and receiver units of the communication set in each of the stations connected into the transmission organization at the 45 same time.

To the accomplishment of the foregoing and such other objects as may hereinafter appear, my invention consists in the elements and their relation one to the other, as hereinafter particularly described and defined in the claims, reference being had to the accompanying drawings which show a preferred embodiment of my invention, and in which:—

Fig. 1 is a diagrammatic view of a portion of 55

- a line illustrating the wayside features of the communication system.
- Fig. 2 is an extension of Fig. 1.
- Fig. 3 is a diagrammatic view of a portion of a railway line illustrating an arrangement of wayside apparatus and circuits which are a modification of those disclosed in Figs. 1 and 2.
- Fig. 4 is a schematic showing of the method of operation of relays O1, O2, etc.
- Fig. 5 is a schematic diagram illustrative of a train operated mechanical circuit closing device.
- Fig. 6 is an elevation of a cross section of a railway track illustrating the relative arrangement of running rails and conductor on the wayside with the coils or inductors carried on the train.
- Fig. 7 is a plan view, schematically showing the arrangement of communication sets on the locomotive and caboose of a train, with reference to the running rails and conductor.
- Fig. 8 is a schematic diagram of the wiring and apparatus comprising a communication set.
- Fig. 9 is a schematic diagram of a modification of the communication set similar to that shown in Fig. 8.
- Fig. 10 is a cross sectional view showing the arrangement of the coils or inductors for a local wayside station with reference to the intermediate circuit.
- Figs. 1 and 2 are intended to be joined together with the right hand end of Fig. 1 connected to the left hand end of Fig. 2 to illustrate the circuit organization and the general arrangement of the system, typical of that for the usual railroad.
- Fig. 3, which illustrates a somewhat different arrangement of wayside circuits at passing siding locations, may be considered as a continuation of Figs. 1 and 2, as hereinafter explained, or it may be considered as a passing siding organization optional with that shown in Figs. 1 and 2.
- In the Figs. 1, 2, and 3, A1 and A2 are the track rails upon which the trains operate. BX represents batteries for track circuits. The insulated joints are illustrated by a short straight line across the heavy line representing the track rails and are generally designated by J1. The condensers connecting the conductors of the intermediate circuits to the track rails are generally designated K1. The condensers which are connected around certain insulated joints are generally designated K2. The track switches are designated S followed by a suffix. The track switches may be operated by means designated by R followed by a suffix which agrees with that for the associated track switch. The track circuit relays are designated T followed by a suffix. Selectors are designated by L followed by a suffix. Relays co-operating with selectors and known as "off and on relays" are designated by O followed by a number which is the same as that for the selector with which used. Relays for automatically connecting intermediate circuit to the dispatcher's communicating circuit are operated in a stick circuit and designated as N relays followed by a suffix. Fixed transpositions of the conductors in the intermediate circuits of the passing siding locations X1 and X2 are generally designated T with a numeral suffix. The inductors or coils for inductively connecting the wayside communication set at local stations and the communication sets on the trains with the intermediate circuit are generally designated U with a numeral suffix. The passing siding tracks are

generally designated PS and the main lines ML. Q1, Q2, Q3 and Q5 represent local wayside communication stations and Q4 the dispatcher's communication stations. The batteries for wayside circuits, other than track circuit batteries, are designated B with a numerical suffix. Circuit closing push keys are designated by the letter P with a numeral suffix.

Figs. 1 and 2 together, and Fig. 3 together with Figs. 1 and 2, or separately, show a stretch of 10 railroad representative of a single track line with passing sidings, comprised in a dispatcher's district, upon which trains operate in both directions and within which trains meet and pass each other. The general arrangement of the 15 wayside circuits and features of the communicating system is illustrated in these figures.

The railroad is divided into sections or blocks A, B, C, D, E, etc. A and Q are shown in Fig. 1 and 3 respectively, as only partial blocks or sections. If A and Q were complete, A would be like block or section G and Q would be similar to section E in arrangement. E-F-G is a stretch of single track between the two passing siding locations X1 and X2 and K to M is the 25 stretch of single track between passing siding locations X2 and X3. The switch operating devices R may be either manually or power operated or some of them may be manually operated and some power operated.

Track circuits are shown where required to operate the various circuits of the communication system as will hereinafter be pointed out. The communication system of my invention is readily operable on a railway line where continuous track circuiting is required for other purposes in which case existing track circuits are used and modified as necessary to serve the communication system, but without interfering with the operation of block signals, or any other similar railway device, which are track circuit controlled. Two forms of track circuits are shown in Fig. 1. The track circuit generally used is well known in the art and comprises a stretch of track with a battery at one end connecting the 45 two rails and a relay at the other end connecting the same two rails. This provides a closed circuit through which electrical energy is flowing at all times. Such circuits are illustrated, for example, in sections B, D, and E. At section 50 F another form of track circuit is illustrated and may be used to advantage, particularly on a railway line not already equipped with track circuits for other purposes. It will be observed that this latter is a normally open track circuit. The 55 relay TF, in series with the battery BX, is connected across the two rails A1 and A2 of a short stretch of track. The length of this stretch need be only 60 to 80 ft., just long enough to insure that there will always be a pair of wheels 60 in the section when a train is passing. Current flows in such a track circuit to operate the relay TF to close its front contacts, only when the section of rails is occupied by a train. The use of such a track circuit results in a saving of electrical energy as compared with the normally closed track circuit where electrical energy is consumed all the time.

Wayside communication or intermediate circuits are provided for the transmission of the 70 communication currents. These are arranged in a manner to best suit local and traffic conditions; for example, at passing siding location X1, the intermediate circuit normally corresponds to the stretch comprising sections B, C and D. For 75

the stretch comprising sections E—F, one intermediate circuit is provided. For the block G another intermediate circuit is provided, etc.

As illustrated in Fig. 3, the intermediate circuit arrangement for the main line outside of passing siding locations, is similar to that described for Figs. 1 and 2; but at passing siding locations, as X3, two intermediate circuits are provided, one for the passing siding track and the other for the main line track. The intermediate circuit for the main line is associated with the stretch comprising sections N, O, and P, while that for the siding normally corresponds to the stretch comprising only a portion of sections N and P and all of section O.

The intermediate circuits illustrated are of two forms, one, such as that for stretch B—C—D, comprising a conductor placed on the ties in the center of both the main track and the passing siding track, makes one complete loop and normally closed circuit associated with both tracks. The other type is that illustrated for stretch E—F, for example, where the conductor, as one side of the intermediate circuit, is located on the ties in the center of the track and the track rails, connected in parallel, act as the other side of the circuit forming a complete loop or normally closed circuit.

For some or all of the passing siding locations, depending upon conditions local to the railroad, I may use the arrangement illustrated for passing siding location X3 of Fig. 3, in which the track rails are used as one side of the intermediate circuit for both the passing siding track and the main track and a conductor connected through condensers to the track rails at both ends of the block for each track, and carried on the ties in the center of the track, forms the other side of the intermediate circuit for each track. This provides one intermediate circuit for the main track and another intermediate circuit for the passing siding track, each electrically isolated from the other.

I have referred to the conductor, which forms one side of the intermediate circuit, as being located on the ties in the center of the track. I prefer this location since practically on all railroad tracks trains are operated at times forward or backward and facing in either direction. Therefore, for such operation the train carried equipment, without any change over arrangement, always co-operates with the wayside equipment. It is obvious, however, that the conductor may be located elsewhere than on the ties in the center of the track. It may be placed on the ends of the ties, but in such case there would need to be a train carried co-operating inductor or coil provided for each side of the train, and generally, a circuit switch adapted to select as between the two inductors for efficient operation.

That station agents, yardmasters and other employes who may be stationed along the railroad may communicate with each other and with trains and, when necessary, with the dispatcher, local communication stations Q1, Q2, Q3, and Q5 are provided. When a train approaches a passing siding location, it automatically operates devices to connect the intermediate circuit for the portion of railway line or block, which includes the passing track, with the dispatcher's communicating circuit, conductors D1 and D2. The same devices which the train automatically operates may also be operated through the circuit closing push keys P, at the local wayside stations Q1, Q2, and Q5 for connecting the intermediate

circuit for the block with the dispatcher's communicating circuit, conductors D1 and D2. The local station Q3, as shown, is not provided with means for initiating communication with the dispatcher.

Q4 represent the dispatcher's communicating station and includes transmitting and receiving communication devices as well as selective equipment for operating relays at remote points as will be hereinafter explained.

Each of the relays O, which are at remote points, is controlled by the associated selector L of the same suffix, and may be of the form shown in Fig. 4. These relays have two positions. Referring to Fig. 4, when the electromagnet of relay T11, for example, is energized, armature 101 is raised, causing the ratchet wheel RW to turn. Since this ratchet wheel is on the same shaft with cam CM, the cam will be operated to make a quarter turn from the position shown and the fingers 23', 12', and 18' will open their front contacts and close their back contacts. When electromagnet T11 is again energized, armature 101 is again operated, turning ratchet wheel RW another quarter of a turn, which causes the cam CM to assume the upright position as shown so that contact fingers 23', 12', and 18' are again closed on their front contacts, etc.

Description of circuits

30

In order to avoid unnecessary repetition and to simplify the description of the system as much as possible, I will now describe a number of representative circuits as they exist under various conditions arising during the practical operation of the system. These circuits are given identifying designations for convenience in referring to them in the description of the operation which follows. The first group of circuits taken up are those for the track sections shown in Figs. 1 and 2. The intermediate circuit and various controlling circuits for each track section are described in order beginning with the circuits for track section A. Following the description of the circuits shown in Figs. 1 and 2, I will describe the corresponding circuits shown in Fig. 3.

The circuits for Figs. 1 and 2 are as follows:

INTERMEDIATE CIRCUITS (BLOCK A AND STRETCH B—C—D)

50

Circuit #1 (Normal intermediate circuit for block including section A and main line to the left thereof)

This intermediate circuit normally includes conductor 1, front contact 2, conductor 3, condensers K1 and the two track rails A1 and A2 in parallel. The left hand end of this circuit which is not shown, will be exactly the same as the left end of the circuit shown for section G.

Circuit #2 (normal intermediate circuit for passing siding location X1, stretch B—C—D)

The intermediate circuit for passing siding location X1, which comprises the stretch B—C—D, normally includes conductor 4, conductor 5 in the center of the passing siding track, transposition T1, conductor 5 in the center of the main line track, front contact 6, conductor 7 in the center of the passing siding track, transposition T1, conductor 7 in the center of the main line track, front contact 8, conductor 9, back contact 10, conductor 11 and back contact 12.

75

Circuit #2a (intermediate circuit for passing siding location X1 when relay O1 is energized)

5 This circuit is the same as Circuit #2 except that the winding *c* of transformer M1 is included therein due to the closure of front contact 12.

10 *Circuit #2b (intermediate circuit for passing siding location X1, stretch B—C—D, when relay N1 is energized)*

15 This intermediate circuit comprises coil *a* of transformer M1, front contact 14, conductor 13, conductor 5 in the center of the siding track, transposition T1, conductor 5 in the center of the main line track, front contact 6, conductor 7 in the center of the passing siding track, transposition T1, conductor 1 in the center of the main line track, front contact 8 and conductors 9 and 15. When front contact 14 is closed, back contact 10 must be open.

20 *Circuit #3 (combined intermediate circuit for block A and stretch B—C—D when relay TA is de-energized)*

25 When relay TA becomes de-energized, contacts 2 and 6 are made on their back points whereby conductor 1 is connected to conductor 7, and the track rails for section A are connected through conductor 3 with conductor 5, thus forming one combined or enlarged intermediate circuit for the blocks comprising section A and stretch B—C—D. Attention is called 30 to the transposition of conductors which takes place when the two individual circuits are combined as a single loop.

35 *Circuit #3a (combined intermediate circuit for block A and stretch B—C—D when connected with dispatcher's communicating circuit, by the energization of relay O1)*

40 This is the same as Circuit #3, excepting coil *c* of transformer M1 is inserted in the circuit.

45 *Circuit #3b (combined intermediate circuit for block A and stretch B—C—D when connected with dispatcher's communicating circuit, by the energization of relay N1)*

50 This is the same as Circuit #3, excepting contact 10 is open and coil *a* of transformer M1 is connected by conductor 15 with conductor 9 and by front contact 14 and conductor 13 with conductor 5.

CONTROLLING CIRCUITS

Circuit #4 (circuit for controlling relay N1 by relays TA and TB)

60 With relays TA and TB de-energized, back contacts 26 and 27 are closed and a circuit is completed for relay N1 from battery B1, conductor 22, contact 23 closed on either its front point or its back point, conductor 24, electromagnet coil N1, conductor 25, back contact 26, back contact 27 and conductors 28 and 29. This circuit causes relay N1 to become energized to close its front contacts 31a, 14, and 21 and open its back contact 10.

65 *Circuit #4a (circuit for controlling relay N1 by push keys P1 and P2)*

70 This circuit is the same as Circuit #4, except that it is completed through the contacts of push

75 keys P1 or P2 instead of through contacts of relays TA, TB, TD and TE.

Circuit #4b (circuit for controlling relay N1 by relays TD and TE)

80 With relays TD and TE de-energized, back contacts 31 and 32 are closed and a circuit is completed for relay N1 from battery B1, conductor 22, contact 23 made on either its front or back point, conductor 24, electromagnet coil N1, conductor 30, back contact 31, back contact 32 and conductors 28 and 29. This circuit is similar in function and arrangement to Circuit #4.

85 *Circuit #4c (circuit for controlling relay N1 by push key P3)*

90 Since contact of push key P3 is in parallel with contacts 31 and 32, the closing circuit for relay N1 is the same as Circuit #4b, except the contact of push key P3 takes the place of contacts 31 and 32.

95 *Circuit #4d (stick circuit for relay N1)*

100 When relay N1 is energized over any one of Circuits #4, #4a, #4b or #4c, it closes front contact 31a, thereby establishing itself energized in a circuit comprising battery B1, conductor 22, contact 23 made on either its front or back point, conductor 24, electromagnet coil N1, conductor 30a, front contact 31a, conductors 32a, 28, and 29.

105 *Circuit #5 (energizing of "off and on" relay O1)*

110 When contact 35 is closed, relay O1 is energized to an abnormal condition in a circuit comprising battery B1, conductors 22 and 37, electromagnet coil O1, conductor 36, contact 35 closed and conductors 34 and 29. The contact 115 35 is usually closed for only a short interval of time. Therefore, it is necessary that relay O1 be arranged to hold its contacts closed in the position to which operated until the electromagnet coil O1 is again energized, due to contact 35 again being closed, when the contacts are shifted 120 to their other position. A relay of this character is illustrated in Fig. 4 and elsewhere described.

125 *Circuit #6 (operation of selector L1)*

130 When the dispatcher's selective equipment DSE disclosed in Fig. 8, is operated, coded impulses of current flow over the dispatcher's communicating circuit, conductors D1 and D2, and conductors 20, 19, 16, and 33 to selector coil L1, 135 which responds to close the contact 35 in a manner hereinafter referred to.

140 *Circuit #7 (connecting primary b of transformer M1 to dispatcher's circuit by relay O1)*

145 When front contact 18 of relay O1 is closed, the primary coil *b* of transformer M1 is connected with conductors D1 and D2 through the circuit comprising conductors 20 and 19, front contact 18 closed, coil *b* and conductor 16.

150 *Circuit #7a (connecting primary b of transformer M1 to dispatcher's circuit by relay N1)*

155 When contact 21 of relay N1 is closed on its front point, a circuit is established connecting primary *b* of transformer M1 to the dispatcher's line, conductors D1 and D2, said circuit comprising conductor 20, front contact 21 closed, coil *b* of transformer M1 and conductor 16.

INTERMEDIATE CIRCUITS (STRETCHES B—C—D AND E—F AND BLOCK G) *Circuit #10a (intermediate circuit for block G with relay O2 energized)*

5 *Circuit #8 (normal intermediate circuit for stretch E—F)*

The normal intermediate circuit for the stretch E—F comprises contact 38 made on its back point, conductor 39, contact 40 made on its back point, conductor 41 carried in the center of the 10 main track between the rails A1 and A2, front contact 42, conductor 43, condensers K1, track rails A1 and A2 in parallel including condensers K2 around insulated joints, condensers K1 in section F and conductor 44.

15 *Circuit #8a (intermediate circuit for stretch E—F with relay O2 energized)*

This circuit is the same as Circuit #8, except that when front contact 38 is closed, coil c of 20 transformer M2 is included in the intermediate circuit.

25 *Circuit #9 (combined intermediate circuit for stretches B—C—D and E—F with relay TE de-energized)*

When contacts 42 and 8 are closed on their back points, conductor 43 is connected through back contact 8 with conductor 7 and conductor 41 is connected through back contact 42 with 30 conductor 9, thus forming one enlarged or combined circuit for the stretches B—C—D and E—F. The connection of the adjacent circuits in this manner produces the effect of a transposition as conductor 7 which lies between the 35 rails of the main line track of block D is connected via contact 8 and conductor 43 to the rails of block E and conductor 41 which lies between the track rails of block E is connected via contacts 42, conductor 9, contacts 10, conductor 11, contacts 12, and conductor 4 to conductor 5 which lies between the rails of the siding of block D.

40 *Circuit #9a (combined intermediate circuit for stretches B—C—D and E—F connected with dispatcher's circuit by relay O1)*

This is the same as Circuit #9, excepting coil c of transformer M1 is inserted in the circuit by the closure of front contact 12.

45 *Circuit #9b (combined intermediate circuit for stretches B—C—D and E—F connected with dispatcher's circuit by relay N1)*

This is the same as Circuit #9, except coil a of transformer M1 is connected by conductor 15 with conductor 9 and by front contact 14 and conductor 13 with conductor 5.

50 *Circuit #9c (combined intermediate circuit for stretches B—C—D and E—F connected with dispatcher's circuit, by relay O2)*

This is the same as Circuit #9, excepting coil c of transformer M2 is inserted in the circuit by the closure of front contact 38.

55 *Circuit #10 (normal intermediate circuit for the block G)*

The normal intermediate circuit for block G comprises back contact 52 closed, conductor 53, 60 back contact 54, conductor 55 in the center of the main line between the track rails A1 and A2, front contact 56 (relay TG, Fig. 2), conductor 57, condensers K1, track rails A1 and A2 in parallel including condensers K2 around insulated joints, 65 condensers K1 and conductor 56a.

The intermediate circuit for block G remains the same as Circuit #10 excepting that it now includes coil a of transformer M2.

65 *Circuit #11 (combined intermediate circuit for stretch E—F and block G with relay TF energized)*

With relay TF energized, contacts 54, 40, and 10 51 are closed on their front points, conductor 41 is connected to conductor 53, and conductor 55 is connected to conductor 39, thus forming one combined or enlarged intermediate circuit for the stretch E—F and block G, and transposing 15 the conductors in relation to each other.

20 *Circuit #11a (combined intermediate circuit for blocks E—F and G connected with dispatcher's circuit, by relay O2)*

This is the same as Circuit #11, except coil c of transformer M2 is inserted in the circuit by the closure of front contact 38. Coil a of transformer M2 is also inserted in the circuit by the closure of front contact 52; but when contact 51 is closed on its front point, conductor 41 is connected through conductor 50 with conductor 56a, thus forming a parallel path with the conductors connected through front contacts 54 and 52 so that the coil a of transformer M2 is shunted. The function of this arrangement is to maintain but one transformer secondary in the combined intermediate circuit for stretch E—F and block G when connection is made with the dispatcher's communication circuit conductors D1 and D2.

CONTROLLING CIRCUITS

25 *Circuit #12 (energizing of "off and on" relay O2)* 40

When contact 35a of selector L2 is closed, relay O2 is energized to an abnormal condition in a circuit comprising battery B2, contact 35a, conductor 36a, electromagnet coil O2 and conductor 37a. Explanation of operation of these "off and on" relays is referred to under Circuit #5 and the construction is shown in Fig. 4.

50 *Circuit #13 (operation of selector L2)*

When the dispatcher's selective equipment, as DSE, shown in Fig. 8 is operated, coded electric current impulses flow over conductors D1 and D2 and 49 and 48 to selector coil L2, thus energizing this coil to close contact 35a as will later 55 be explained.

55 *Circuit #14 (Primary b of transformer M2 connected to the dispatcher's circuit, by relay O2)*

When contact 46 of relay O2 is closed on its 60 front point, primary b of transformer M2 is connected to the dispatcher's line, i.e., conductors D1 and D2, through conductor 45, coil b of transformer M2, front contact 46 and conductors 47 and 48.

65 *INTERMEDIATE CIRCUITS (BLOCK G AND STRETCH H—I—J)*

70 *Circuit #15 (normal intermediate circuit for passing siding location X2, stretch H—I—J)* 70

The intermediate circuit for passing siding location X2 which includes the stretch H—I—J, normally includes conductor 58, conductor 59 in the center of the passing siding track, transposi- 75

tion T2, conductor 59 in the center of the main line track, front contact 60, conductor 61 in the center of the passing siding track, transposition T2, conductor 61 in the center of the main line track, front contact 62, conductor 63, back contact 64, conductor 65 and back contact 66.

Circuit #15a (intermediate circuit for passing siding location X2, stretch H—I—J, with relay O3 energized)

10 This intermediate circuit is the same as intermediate Circuit #15 except that it includes secondary coil c of transformer M3.

15 *Circuit #16 (intermediate circuit for passing siding location X2, stretch H—I—J, with relay N2 energized)*

20 This is the same as Circuit #15, except coil a of transformer M3 is connected in the circuit by conductor 69 and front contact 68 and conductor 67. Contact 64 which is in parallel with contact 68, is open.

25 *Circuit #17 (combined intermediate circuit for block G and stretch H—I—J, with relay TG de-energized)*

30 With relay TG de-energized, contacts 56 and 60 are made on their back points, conductor 55 is connected to conductor 61, and the track rails A1 and A2 for block G are connected via conductor 57 and back contact 60 with conductor 59, thus forming one combined or enlarged intermediate circuit for the block G and stretch H—I—J.

35 *Circuit #17a (combined intermediate circuit for block G and stretch H—I—J connected with dispatcher's circuit by relay O3)*

40 This is the same as Circuit #17, excepting coil c of transformer M3 is inserted in the circuit.

45 *Circuit #17b (combined intermediate circuit for block G and stretch H—I—J connected with dispatcher's circuit by relay N2)*

50 This is the same circuit as #17, excepting contact 64 is open, and coil a of transformer M3 is connected by conductor 69 with conductor 63 and by front contact 68 and conductor 67 with conductor 59.

55 *Circuit #17c (combined intermediate circuit for block G and stretch H—I—J connected with dispatcher's circuit by relay O2)*

60 This is the same as Circuit #17, excepting back contact 52 is opened and front contact 52 is closed, inserting coil a of transformer M2 in the circuit.

CONTROLLING CIRCUITS

65 *Circuit #18 (circuit for controlling relay N2 by relays TG and TH)*

70 With relays TG and TH de-energized, back contacts 80 and 81 are closed and a circuit is completed for relay N2 from battery B3, conductor 76, contact 77, closed on either its front point or its back point, conductor 78, electromagnet coil N2, conductor 79, back contacts 80 and 81, and conductors 82 and 83. This circuit causes relay N2 to become energized.

75 *Circuit #18a (circuit for controlling relay N2 by push keys P4 and P5)*

80 The contact keys P4 and P5 are in parallel with each other and with contacts 80 and 81 and either push key contact may replace contacts 76 80 and 81 in Circuit #18.

Circuit #18b (circuit for controlling relay N2 by relays TJ and TK)

85 With relays TJ and TK de-energized, back contacts 85 and 86 are closed and a circuit is completed for relay N2 comprising battery B3, conductor 76, contact 77 made on either its front or back point, conductor 78, electromagnet coil N2, conductor 84, back contacts 85 and 86 and conductors 82 and 83. This circuit is similar in function and arrangement as Circuit #18. 10

90 *Circuit #18c (circuit for controlling relay N2 by push key P6)*

95 Contact of push key P6 replaces contacts 85 and 86 in Circuit #18b.

100 *Circuit #19 (stick circuit for relay N2)*

105 When relay N2 is energized in the Circuits #18, #18a, #18b or #18c, it closes front contacts 85a, thereby maintaining itself energized in a circuit 20 comprising battery B3, conductor 76, contact 77 made on either its front or back point, conductor 78, electromagnet coil N2, conductor 84a, front contact 85a and conductors 86a, 82, and 83. 25

110 *Circuit #20 (energizing of "off and on" relay O3)*

115 When contact 89 of selector L3 is closed, relay O3 is energized to an abnormal condition in a circuit comprising battery B3, conductors 76 and 91, electromagnet coil O3, conductor 90, contact 89 closed and conductors 88 and 83. The contact 89 is usually closed for only a short interval of time. Therefore, it is necessary that relay O3 be arranged to hold its contacts closed in the position to which operated until the electromagnet coil O3 is again energized, due to contact 89 again being closed when the contacts are shifted to their other position. A relay of this character is illustrated in Fig. 4 and elsewhere 40 described. 35

120 *Circuit #21 (operation of selector L3)*

125 When the dispatcher's selective equipment DSE shown in Fig. 8 is operated, coded impulses 45 of current flow over the dispatcher's communicating circuit, conductors D1 and D2 and conductors 70, 87, 74, and 73 to selector coil L3 which responds to close the contact 89, as will 50 be later described.

130 *Circuit #22 (connecting primary b of transformer M3 to dispatcher's circuit by relay O3)*

135 When front contact 72 is closed, the primary 55 coil b of transformer M3 is connected with conductors D1 and D2 through the circuit comprising conductors 74 and 73, front contact 72 closed, coil b and conductor 70.

140 *Circuit #23 (similar to Circuit #22 but when contact 75 is closed)*

145 When contact 75 is closed on its front point a circuit is established, connecting primary b of transformer M3 to dispatcher's line, i. e., conductors D1 and D2, said circuits comprising conductor 74, front contact 75 closed, coil b and conductor 70. 65

150 *INTERMEDIATE CIRCUITS (STRETCH H—I—J AND BLOCK K)*

155 *Circuit #24 (normal intermediate circuit for block K)*

This intermediate circuit normally includes the track rails A1 and A2 in parallel, condensers 75

K2 around insulated joints, condensers K1, conductor 92, front contact 93 and conductor 94 in the center of the main track between the rails A1 and A2. The right hand end of this circuit 5 which is not shown will be similar to the right end of the circuit shown for stretch E-F. Normally, this circuit is closed.

Circuit #24a (combined intermediate circuit for stretch H-I-J and block K with relay TK de-energized)

When contacts 93 and 62 are made on their back points, as when there is a train in the track 15 circuit for relay TK, conductor 94 is connected to conductor 63, and conductor 61 is connected to conductor 92 and the track rails A1 and A2 for block K, thus forming one combined or enlarged intermediate circuit for the stretch H-I-J and block K.

20 The circuits for Fig. 3 are as follows:

INTERMEDIATE CIRCUITS (BLOCK M AND STRETCH N-O-P)

25 *Circuit #25 (normal circuit for block M)*

This intermediate circuit normally includes conductor 181, front contact 182, conductor 183, condensers K1 and the two track rails A1 and A2 in parallel and including any condensers K2 30 which there may be around insulated joints in the track rails. The left hand end of this circuit is not shown, but is the same as the left hand end of the circuit illustrated for block G. Normally, this circuit is closed. If Fig. 3 is 35 made a continuation of Fig. 2, there would need to be an intervening section L, like F with its track relay TF, off and on relay O2, transformer M2 and selector L2, between the blocks K and M. This would provide for communication between trains and the dispatcher.

Circuit #26 (normal intermediate circuit for main line at passing siding location X3, stretch N-O-P)

45 The intermediate circuit for passing siding location X3, which includes the track sections N, O, and P, normally includes conductors 102 and 103, condensers K1, main line track rails A1 and A2 in parallel, condensers K2 as required, around insulated joints in the track rails, condensers K1 at the left hand end of section N, conductor 104, front contact 105, conductor 106, contact 107, closed when switch S5 is normal, conductor 108 located in the center of the main track, contact 109 closed when switch S6 is normal, conductor 110, front contact 111, conductor 112, back contact 113, conductor 114 and back contact 115.

60 *Circuit #26a (intermediate circuit for main line at passing siding location X3 with relay O5 energized)*

This is the same as Circuit #26 above described, excepting that secondary c of transformer M5 is now inserted in the circuit.

Circuit #26b (intermediate circuit for main line at passing siding location X3 with relay N4 energized)

70 When contact 154 is closed, back contact 113 must be opened. This circuit is the same as Circuit #26, excepting that the secondary a of transformer M5 is inserted in the circuit through conductors 155 and 153.

Circuit #27 (normal intermediate circuit for passing siding PS at location X3)

This circuit comprises track rails A1' and A2' in parallel, condensers K2 as required around insulated joints in these track rails, condensers K1 connecting to track rails A1' and A2', contact 120 closed when switch S5 is normal, conductor 121, conductor 122 in center of passing siding track, back contact 123, conductor 124, back contact 125, conductor 116, conductor 117 10 in center of passing siding track, contact 118 closed when switch S5 is normal, condensers K1 and track rails A1' and A2' at the left hand end of the passing siding.

Circuit #27a (circuit for passing siding PS at location X3 with relay O4 energized)

This is the same as Circuit #27 above described, excepting that secondary a of transformer M4 is now inserted in the circuit.

Circuit #27b (intermediate circuit for passing siding PS at location X3 with relay N3 energized)

25 With relay N3 energized, front contact 163 is closed and back contact 123 must be opened. This circuit is the same as Circuit #27, excepting that secondary c of transformer M4 is inserted in the circuit through closed contact 163 30 and conductors 162 and 165.

Circuit #28 (intermediate circuit at passing siding location X3 when track switch S5 is reversed)

35 When track switch S5 is reversed, the intermediate circuit comprises track rails A1 and A2 in parallel, condensers K2 around insulated joints in these track rails, condensers K1, conductor 104, front contact 105, conductor 106, contact 127 now closed since switch S5 is reversed, conductor 119, condensers K1, track rails A1' and A2' in parallel, condensers K2 around insulated joints in these track rails, condensers K1 at the right hand end of the siding track, contact 120 closed as the switch S5 is normal, conductor 121, 45 conductor 122 in the center of the passing siding track, back contact 123, conductor 124, back contact 125, conductor 116, conductor 117 in the center of passing siding track, contact 126 closed since switch S5 is reversed, conductor 108 50 in the center of main line track, contact 109 closed as switch S6 is normal, conductor 110, front contact 111, conductor 112, back contact 113, conductor 114, back contact 115, conductors 102 and 103, condensers K1 and track rails A1 and A2 at the right hand end of section P. It will be observed that under conditions where track switch S5 is reversed, the two intermediate or loop circuits, one for the passing siding PS, the other for the main line ML, are now 55 connected in series as one circuit.

Circuit #28a (intermediate circuit at passing siding location X3 when track switch S5 is reversed and relay N4 is energized)

65 This is the same circuit as #28 except coil a of transformer M5 is inserted in the circuit when contact 154 is closed, and coil b is connected to the conductors D1 and D2 through front contact 156.

Circuit #28b (intermediate circuit at passing siding location X3 when track switch S5 is reversed and relay N3 is energized)

This is the same circuit as #28 except coil c 75

of transformer M4 is inserted in the circuit when front contact 163 is closed and coil b is connected to the conductors D1 and D2 through front contact 166.

- 6 *Circuit #28c (intermediate circuit at passing siding location X3 when track switch S5 is reversed and relays N3 and N4 are energized)*

This is the same as Circuit #28a, except coil c of transformer M4 is also inserted in the circuit when front contact 163 is closed, and coil b is connected to the conductors D1 and D2 through front contact 166. It will be noted that this intermediate circuit is a combination in series 10 of intermediate Circuits #26b and #27b.

- 15 *Circuit #29 (intermediate circuit at passing siding location X3 when switch S6 is reversed)*

This circuit is similar to Circuit #28, excepting 20 that in this case, switch S6 is reversed and switch S5 is normal. With switch S6 reversed, contacts 120 and 109 are opened and contacts 127' and 128 are closed. The intermediate or 25 loop circuits for the passing siding track and the main line track, both in the stretch N—O—P at the location X3, are now connected together in series as one circuit, comprising, track rails A1 and A2 in parallel, condensers K2 around insulated joints, condensers K1, conductor 104, front contact 105, conductor 106, contact 107, conductor 108 in the center of the main line track, contact 127' closed as track switch S6 is reversed, conductor 121, conductor 122 in center 30 of siding track, back contact 123, conductor 124, back contact 125, conductor 116, conductor 117 in center of siding track, contact 118, conductor 119, condensers K1, siding track rails A1' and A2', condensers K2 around insulated joints in siding track rails, condensers K1, contact 128 35 closed as switch S6 is reversed, conductor 110, front contact 111, conductor 112, back contact 113, conductor 114, back contact 115, conductors 102 and 103 and condensers K1, connected to track rails A1 and A2 at right end of stretch 40 N—O—P.

- 45 *Circuit #29a (intermediate circuit at passing siding location X3 when track switch S6 is reversed and relay N4 is energized)*

50 This circuit is the same as #29, except the coil a of transformer M5 is inserted in the circuit when contact 154 is closed and coil b is connected to the conductors D1 and D2 through front contact 156.

- 55 *Circuit #29b (intermediate circuit at passing siding location X3 when track switch S6 is reversed and relay N3 is energized)*

60 This is the same circuit as #29, except coil c of transformer M4 is inserted in the circuit when front contact 163 is closed, and coil b is connected to the conductors D1 and D2 through front contact 166.

- 65 *Circuit #29c (intermediate circuit at passing siding location X3 when track switch S6 is reversed and relays N3 and N4 are energized)*

70 This is the same as Circuit #29a, except coil c of transformer M4 is also inserted in the circuit and coil b is connected to the conductors D1 and D2 through front contact 166. It will be noted that this intermediate circuit is a combination in series 75 of intermediate Circuits #26b and #27b.

Circuit #29 (A and B)—(intermediate circuit arrangement at location X3 when passing siding switches S5 and S6 are both reversed)

Under this condition, two intermediate circuits exist in parallel for the main line track and the siding track at location X3:

(A) This intermediate circuit comprises conductor 116, conductor 117 in the center of passing siding track, contact 126 closed since switch S5 is reversed, conductor 108 in the center of 10 main line track, contact 127' closed since switch S6 is reversed, conductor 121, conductor 122 in the center of passing siding track, contact 123, conductor 124 and contact 125.

With contact 125 closed on its front point, secondary a of transformer M4 is connected into the intermediate circuit just described and with contact 169 closed on its front point, primary coil b of transformer M4 is connected to conductors D1 and D2 of the dispatcher's communicating circuit.

With contacts 163 and 166 closed on their front points, secondary c of transformer M4 is inserted in this intermediate circuit and primary b of transformer M4 is connected to conductors D1 and D2 of the dispatcher's communicating circuit.

With contacts 102 and 105 made on their back points with switches S5 and S6 both reversed, intermediate Circuit #29A does not form a part 30 of the combined intermediate circuit for block M and stretch N—O—P.

With contacts 180 and 111 closed on their back points, intermediate Circuit #29A does not form a part of the combined intermediate circuit for 35 stretch N—O—P and block Q.

(B) This intermediate circuit comprises main track rails A1 and A2 in parallel including the condensers K2 around insulated joints, condensers K1, conductor 104, front contact 105, conductor 106, contact 127 closed since switch S5 is reversed, conductor 119, condensers K1, the two track rails A1' and A2', condensers K1 at the right hand end of the passing siding at location X3, contact 128 closed since switch S6 is reversed, conductor 110, front contact 111, conductor 112, back contact 113, conductor 114, back contact 115, conductors 102 and 103, condensers K1 at the right hand end of section P and track rails A1 and A2.

With contact 115 closed on its front point, secondary c of transformer M5 is inserted in the intermediate circuit. When contact 115 is closed on its front point, contact 159 must also be closed on its front point, thus connecting primary b of transformer M5 to conductors D1 and D2 of the dispatcher's communicating circuit.

With front contacts 154 and 156 closed, secondary a of transformer M5 is inserted in this intermediate circuit and primary b of transformer M5 is connected to the conductors D1 and D2 of the dispatcher's communicating circuit.

With contacts 182 and 105 closed on their back points, intermediate Circuit #29B is included as a part of the combined intermediate circuit for 65 stretch N—O—P and block Q.

With contacts 180 and 111 closed on their back points, intermediate Circuit #29B is included as a part of the combined intermediate circuit for stretch N—O—P and block Q.

Circuit #30 (intermediate circuits for block M and for main line track of stretch N—O—P combined as one circuit)

When contacts 182 and 105 of relay T5 are 75

made on their back points, conductor 181 is connected through conductor 104 to the track rails A1 and A2 of section N and the track rails for section M are connected through conductor 183 and back contact 105 with conductor 106, thus forming one combined or enlarged intermediate circuit comprising the block M and stretch N—O—P. If the switch S5 is normal, this combined intermediate circuit exists for the main line track only.

Circuit #30a (intermediate circuit for block M and for passing siding track PS of stretch N—O—P combined as one circuit when switch S5 is reversed)

When contacts 182 and 105 of relay T5 are made on their back points, conductor 181 is connected through conductor 104 with the track rails A1 and A2 of section N and the track rails for section M are connected through conductor 183 with conductor 106. With switch S5 reversed, contacts 118 and 107 are opened and contacts 126 and 127 closed; hence, conductor 106 is connected via contact 127 with the track rails A1' and A2' of the passing siding track and conductor 117 is connected via contact 126 with conductor 108. Therefore, this combined intermediate circuit includes the intermediate circuit for the main line track ML connected in series with the intermediate circuit for the passing siding track PS.

Circuit #30b (intermediate circuit for block M and for passing siding track of stretch N—O—P combined as one circuit when switch S6 is reversed)

When contact 182 and 105 are made on their back points, conductor 181 is connected through conductor 104 with the track rails A1 and A2 of section N and the track rails for section M are connected through conductor 183 with conductor 106. With switch S6 reversed, contacts 120 and 109 are opened and contacts 127' and 128 are closed, hence, conductor 110 is connected via contact 128 with the track rails A1' and A2' of the passing siding track and conductor 108 is connected via contact 127' with conductor 122. Therefore, this combined intermediate circuit includes the intermediate circuit for the main line ML connected in series with the intermediate circuit for the passing siding PS.

Circuit #30c (intermediate circuit for block M and for passing siding track of stretch N—O—P combined as one circuit when both switches S5 and S6 are reversed)

When contacts 182 and 105 of relay T5 are made on their back points, conductor 181 is connected through conductor 104 with the track rails A1 and A2 of section N and the track rails for section M are connected through conductor 183 with conductor 106. With switch S5 reversed, contacts 118 and 107 are opened and contacts 126 and 127 are closed; hence, conductor 106 is connected via contact 127 with conductor 119 and the track rails A1' and A2' and conductor 117 is connected via contact 126 with conductor 108. With switch S6 reversed, contacts 120 and 109 are opened and contacts 127' and 128 are closed; hence, conductor 108 is connected via contact 127' with conductor 122. Therefore, this combined intermediate circuit includes the parallel connected track rails A1 and A2 of the main line in series with the paral-

lel connected track rails A1' and A2' of the passing siding. The center of track conductors of both the main line and the passing siding are connected together to form a closed intermediate circuit, for both the main line and the passing siding of the stretch N—O—P, which is in no way connected in the combined intermediate circuit for the block M and stretch N—O—P when contacts 182 and 105 are closed on their back points.

10

CONTROLLING CIRCUITS

Circuit #31 (circuit for controlling relay N4 by relay T6)

When back contact 130 is closed, this circuit comprises battery B5, conductor 134, contact 133 made on either its front or back point, conductor 132, electromagnet coil N4, conductor 131, back contact 130 and conductors 129, 136 and 175. The closing of this circuit energizes relay N4 closing its front contacts 137, 154 and 156 and opening its back contact 113. Front contact 137 completes a stick circuit for relay N4 comprising battery B5, conductor 134, contact 133 made in either position, conductor 132, electromagnet coil N4, front contact 137, and conductors 138, 136 and 175. Since the push key P7 is in parallel with back contact 130, the operation of this key to close its contact will also result in relay N4 being energized and stuck in a circuit through its contact 137. The push key P7 may be located near one of the track switches S5 or S6 or at a point convenient for trains to stop or in a wayside station or there may be several of these push keys in parallel arrangement at each of the various locations named. Back contact 139, which is also arranged in parallel with contact 130, when closed, will cause energization of relay N4 as heretofore explained, with the result that relay N4 will remain energized in a circuit created through its front contact 137, as also heretofore explained.

Circuit #32 (circuit for controlling relay N3 by relay T7)

When back contact 141 of relay T7 is closed, relay N3 is energized in a circuit comprising battery B4, conductor 146, contact 145 made on either its front or back point, conductor 144, electromagnet coil N3, conductors 143, conductor 142, back contact 141 and conductor 129. When relay N3 is energized, contacts 150, 163 and 166 are closed on their front points and back contact 123 is opened. With the closing of front contact 150, relay N3 is established in the stick circuit comprising battery B4, conductor 146, contact 145 made on either its front or back point, conductor 144, contact 150, conductors 151 and 129 to the other pole of battery B4. Since push key P6 is connected in parallel with back contact 141, its operation to close its contact will result in this circuit being established as just described. The same is true for back contact 152 which is also in parallel with back contact 141.

Circuit #33 (operation of selector L5)

When the dispatcher's selective equipment DSE (Fig. 8) is operated, coded impulses of current flow over the dispatcher's communicating circuit, conductors D1 and D2 and conductors 158 and 161, 160 and 157 to selector coil L5 which responds to close the contact 177, as will be later described.

75

Circuit #43 (energizing of "off and on" relay O5)

When contact 177 of selector L5 is closed, the relay O5 is energized to an abnormal condition in a circuit comprising battery B5, conductor 134, electromagnet coil O5, conductor 178, contact 177 closed and conductors 176 and 175. The contact 177 is usually closed for only a short interval of time. Therefore, it is necessary that relay O5 is arranged to hold its contacts closed in the position to which operated until the electromagnet coil O5 is again energized, due to contact 177 again being closed when relay O5 is again operated to return its contacts to the other of the two positions.

Circuit #35 (connecting primary b of transformer M5 to dispatcher's circuit when relay O5 is energized)

When front contact 159 of relay O5 is closed, the primary coil b of transformer M5 is connected with conductors D1 and D2 through the circuit comprising conductors 157, 160, and 174, front contact 159 closed, coil b and conductor 158.

Circuit #35a (connecting primary b of transformer M5 to dispatcher's circuit when relay N4 is energized)

When front contact 156 of relay N4 is closed, the primary coil b of transformer M5 is connected with conductors D1 and D2 through the circuit comprising conductor 157, closed front contact 156, coil b and conductor 158.

Circuit #36 (operation of selector L4)

When the dispatcher's selective equipment DSE (Fig. 8) is operated, coded impulses of current flow over the dispatcher's communicating circuit, conductors D1 and D2 and conductors 172, 173, 174 and 161 to selector coil L4 which responds to close the contact 148, as will be later described.

Circuit #37 (energizing of "off and on" relay O4)

When contact 148 of selector L4 is closed, relay O4 is energized to an abnormal condition in a circuit comprising battery B4, conductor 146, electromagnet coil O4, conductor 147, contact 148 and conductors 149, 136 and 129 to the other pole of battery B4. Since the contact 148 is usually closed for only a short interval of time, it is necessary that relay O4 be arranged to hold its contacts closed in the position to which operated until the electromagnet coil O4 is again energized due to contact 148 again being closed when relay O4 is again returned to the other of its two positions.

Circuit #38 (connecting primary b of transformer M4 to dispatcher's circuit when relay O4 is energized)

When front contact 169 of relay O4 is closed, the primary coil b of transformer M4 is connected with conductors D1 and D2 through the circuit comprising conductors 167, 171, and 170, closed front contact 169, coil b and conductor 172.

Circuit #38a (connecting primary b of transformer M4 to dispatcher's circuit when relay N3 is energized)

When front contact 166 of relay N3 is closed, the primary coil b of transformer M4 is connected with conductors D1 and D2 through the circuit comprising conductor 167, closed front

contact 166, conductor 168, coil b and conductor 172.

INTERMEDIATE CIRCUITS*Circuit #39 (normal intermediate circuit for block Q)*

This circuit, which is but partly shown comprises track rails A1 and A2, including condensers K2 around insulated joints, condensers K1, conductor 179, front contact 180 and conductor 181' 10 in the center of the main line track ML. The incompletely part of this circuit is similar to that shown at the right hand end of section E and section F of Fig. 1. Normally, the circuit is closed.

Circuit #40 (the intermediate circuit for main line track of stretch N—O—P combined with intermediate circuit for block Q, when relay T10 is de-energized)

When contacts 180 and 111 of relay T10 are closed on their back points, conductor 181' is connected to conductor 112 through back contact 180 and conductor 179 is connected through back contact 111 with conductor 110, thus connecting together the normal intermediate Circuits #26 and #39, forming one enlarged or combined intermediate circuit for the main line track of stretch N—O—P and the block Q.

Circuit #40a (intermediate circuit for main line track of stretch N—O—P combined with intermediate circuit for block Q when relay O5 is energized)

This circuit is the same as Circuit #40, except that, with contact 115 closed on its front point, coil c of transformer M5 is now inserted in the circuit.

Circuit #40b (intermediate circuit for main line track of stretch N—O—P combined with the intermediate circuit for block Q, when relay N4 is energized)

This circuit is the same as Circuit #40, except that with the closing of front contact 154, coil a 45 of transformer M5 is connected in the Circuit #40 through conductor 155, front contact 154 and conductor 153. Back contact 113 being open, the circuit by way of contact 115 is open.

Circuit #41 (intermediate circuit for block Q and for passing siding track PS and main line track ML of stretch N—O—P combined as one circuit when track switch S5 is reversed and relay T10 is de-energized)

When contacts 180 and 111 of relay T10 are closed on their back points, conductor 181' is connected to conductor 112 and conductor 179 is connected with conductor 110. With switch S5 reversed, contacts 118 and 107 are opened and contacts 126 and 127 are closed, hence conductor 106 is connected via contact 127 to the track rails A1' and A2' of the passing siding track and conductor 117 is connected via contact 126 with conductor 108. Therefore, this combined intermediate circuit includes the intermediate circuit for the main line track ML connected in series with the intermediate circuit for the passing siding track PS.

Circuit #42 (intermediate circuit for block Q and intermediate circuits for passing siding track PS and main line ML of stretch N—O—P combined when track switch S6 is reversed)

When contacts 180 and 111 of relay T10 are 75

closed on their back points, conductor 181' is connected to conductor 112 and conductor 179 is connected to conductor 110. With switch S6 reversed, contacts 120 and 109 are opened and

5 contacts 127' and 128 are closed; hence conductor 110 is connected via contact 128 with the track rails A1' and A2' of the passing siding track and conductor 108 is connected via contact 127' with conductor 122. Therefore, this combined intermediate circuit includes the intermediate circuit for the main line ML connected in series with the intermediate circuit for the passing siding PS.

15 *Circuit #42a (intermediate circuit for block Q, and for passing siding track PS and main line track ML of stretch N—O—P when track switch S6 is reversed, relay T10 is de-energized and relay N3 is energized)*

20 This circuit is the same as #42, except coil c of transformer M4 is inserted in the circuit through conductor 162, front contact 163 and conductor 165, and coil b is connected to the conductors D1 and D2 through conductor 172, contact 166 and conductor 167.

25 *Circuit #42b (intermediate circuit for block Q, and for passing siding track PS and main line track ML of stretch N—O—P when track switch S6 is reversed, relay T9 is de-energized, relay T10 is de-energized and relay N4 is energized)*

30 This circuit is the same as Circuit #42, except coil a of transformer M5 is inserted in the circuit through conductor 155, contact 154 and conductor 153 and coil b is connected to the conductors D1 and D2 through conductor 158, contact 156 and conductor 157.

35 *Circuit #42c (intermediate circuit for block Q and for passing siding track PS and main line track ML of stretch N—O—P when track switch S6 is reversed relay T10 is de-energized and relays N3 and N4 are energized)*

40 This circuit is the same as #42 except that with relays N3 and N4 both energized. There is a connection through both transformers M4 and M5 with the dispatcher's communicating circuit conductors D1 and D2. This circuit is a combination of the circuit arrangement indicated for Circuits #42a and #42b.

45 *Circuit #43 (intermediate circuit for block Q and for passing siding track of stretch N—O—P combined when both switches S5 and S6 are reversed and relay T10 is de-energized)*

50 When contacts 180 and 111 of relay T10 are closed on their back points, conductor 181' is connected to conductor 112 and conductor 179 is connected with conductor 110. This combined intermediate circuit includes the parallel connected track rails A1 and A2 of the main line in series with the parallel connected track rails A1' and A2' of the passing siding as is described for Circuit #29B. The center of track conductors of both the main line and the passing siding are connected together to form a closed intermediate circuit, for both the main line and the passing siding of stretch N—O—P which is in no way connected in the combined intermediate circuit for the stretch N—O—P and block Q when contacts 180 and 111 are closed on their back points.

55 The block and intermediate circuit arrangement between passing siding locations, where the

circuit arrangement at any one or more than one passing siding location is as illustrated in Fig. 3, is on the order of that shown between the location X1 and X2 of Figs. 1 and 2.

The circuits above described are generally representative of the arrangement of circuits for the equipping of the railway line in a dispatcher's district. These circuits for any of the equipped tracks are arranged to function for trains operating in either direction or running forward or backward, and to always provide an intermediate circuit connecting together communication stations at different points on a train. The intermediate circuit for any stretch or block is normally electrically isolated from the intermediate circuit of any other stretch or block. Means are also provided for each intermediate circuit to be connected to the dispatcher's communicating circuit, conductors D1 and D2.

60 Before proceeding with a description of the operation of the system, the circuits and apparatus shown in Figs. 5 to 10, inclusive, will be described in detail.

65 Fig. 5 diagrammatically illustrates a track contactor, designed to operate when a train passes, which may be used to close the circuits of the controlling relays N to automatically connect intermediate circuits with the dispatcher's communicating circuit, conductors D1 and D2. For example, such a contactor may be used instead of the relay T1, Fig. 3, the contact 191 being substituted in the circuit for contact 141 so that conductor 192 replaces conductor 142 and conductor 193 is connected to conductor 129. A contactor of this description may be used at any point where relays are shown for the purpose of energizing the control relays N. In operation, the end of the lever 190, which is next to the track rail A1 is depressed by the tread of passing train wheels so that the outer end of the lever is elevated, closing the contact 191. As is obvious, the lever 190 may be so located under the base of the rail A1 as to close the contact 191 when passing wheels deflect the rail A1 downward. Ordinarily, a mechanical contactor is less expensive for installation and operation than a track circuit and relay.

70 Fig. 6 is an elevation view of the arrangement of a train carried communication set with reference to the track rails and the wayside intermediate circuit system. Q6 diagrammatically represents the communication set or station on a train. This communication set shown in detail in Fig. 8 is in circuit with inductors U6, U7 and U8. The inductors U6 and U8 are located near the track rails A1 and A2, respectively, and so as to be in inductive relation through an air gap with these track rails. Inductor U7 is located near conductor CON and in inductive relation therewith through an air gap. The coils of inductors U6, U7, and U8 are connected in aiding relation, it being remembered that at any instant the flow of communicating current is in the same direction in track rails A1 and A2 and in the opposite direction in the conductor CON.

75 Fig. 7 is a plan view of the arrangement of communicating sets at different points on trains relative to the intermediate circuit; for example, with one communicating set on the caboose CA and the other on the locomotive LO. The arrangement of each set, when viewed in elevation, is like that shown in Fig. 6. The details of the transmitting and receiving equipment are illustrated in Fig. 8. On transmitting a mes-

sage from set Q1, inductors U9 and U11 induce communicating electric currents, corresponding to the transmitted message, in the track rails A1 and A2 to flow in the same direction at any instant, while the inductor U10 induces the communicating current into the conductor CON to flow at the same said instant in a direction opposite to the flow of current in the two track rails. Since the conductor CON forms one side 5 of the intermediate circuit and is connected at the ends of the block to the two track rails which function in parallel, forming the other side of the intermediate circuit, as heretofore explained, the communicating currents originating in the set Q1 flow in the intermediate circuit and are received by the inductors U12, U13 and U14 from the track rail A1, the conductor CON and the track rail A2, respectively. These latter inductors are normally in circuit with the 10 responsive device, such as a telephone receiver, which forms a part of the set Q8. Similarly, when set Q8 transmits, the receiver of Q1 is in circuit with the inductors so that the transmitted current, which is induced by the inductors into 15 the track rails A1 and A2 to flow therein in parallel and conductor CON to flow in the direction opposite to that of the current in the track rails, is reinduced into the inductors U9, U11, and U10 respectively and carried to the receiver, forming a part of the set Q1. Thus, communication messages, such as telephone messages, 20 may be transmitted back and forth between the two train points.

Fig. 8 is a diagram of the details of the 25 communicating sets carried on the train and in the wayside stations. That part of the diagram encompassed in the boundary line 1, 2, 3, 4, comprises the selective and communicating equipment for the dispatcher's station, represented by the symbol Q4 of Fig. 2, for which conductor 203 would be connected to conductor 100 and conductor 204 to conductor 99.

DSE is the dispatcher's selective equipment, heretofore referred to, of the type similar to the 30 Gill or the Western Electric systems in common use on the railroads for train dispatching and may be of the type used in telephone systems for selecting between subscribers. It is arranged so that coded impulses of electric current of different characteristics may be sent out over the 35 dispatcher's line, conductors D1 and D2, from the dispatcher's station. Located as may be required, along the railroad within the dispatcher's district, are the selectors L1, L2, L3, etc., as heretofore explained. Each selector is responsive to 40 close its contacts for one particular combination of impulses and not for any other combination of impulses. The dispatcher, desiring to operate selector L1, for example, sends out a code of current impulses to which this selector will respond, but to which selectors L2, L3, etc., will not respond to close their contacts. Selector L1, in responding, closes its contact 35 in circuit with "off and on" relay O1, the operation of 45 which has been heretofore explained in Circuit #5.

Included within the boundary line, 2, 3, 4, 5, is illustrated the communicating set which may be used in the dispatcher's office, in connection 50 with the selective equipment described, and which is also suitable for use with communication sets, such as Q1 and Q8, for a train and for the wayside communication stations Q1, Q2, Q3 and Q5. For train use, conductors 203 and 204 55 are connected, for example, to conductors 194

and 197 respectively for station Q1 and to conductors 198 and 201 for station Q8. For the wayside stations, conductors 203 and 204 are connected respectively to conductors 95 and 96 for wayside station Q1, conductors 95' and 96' for station Q2 and to conductors 97 and 98 for station Q3.

In the arrangement of the communicating set for station Q5 (Fig. 3) conductor 203 is connected to the switch C11 and conductor 204 is 10 connected to the conductors 135 and 184. In this arrangement one communicating set is suitable to be used with either inductor set U4 or inductor set U5. In the event communicative relation of station Q5 with the intermediate circuit for the main line (Circuits #26, #26a, and #26b) and the intermediate circuit for the passing siding (Circuits #27, #27a, and #27b) is required at all times, one communication set may be connected directly with inductor set U4 and 15 20 another communicating set with inductor set U5. As an alternative, receiver equipment may be normally in circuit with each inductor set and one transmitter equipment provided for connection to either as required. With either switch S5 or S6 open (reversed) so that the intermediate circuit for the main line is combined with the intermediate circuit for the passing siding (Circuits #28, #28a, #28b, and #28c and Circuits #29, #29a, #29b, and #29c) both inductor 30 sets U4 and U5 are in inductive relation with the combined circuit. With both switches S5 and S6 open (reversed) the inductors a and c of both sets U4 and U5 are in inductive relation with the intermediate circuit (Circuit #29B), 35 which includes the track rails, and the inductors b of each set are in inductive relation with the intermediate circuit (Circuit #29A), which includes the center of track conductors.

The communication equipment in Fig. 8 comprises a receiver or loud speaker LS normally in circuit with a transformer M7 by reason of the switch C1 being maintained normally in position a by a spring or other device 2a'. This circuit comprises conductors 220 and 221, amplifier AQ, 40 conductor 218 containing the switch C5 and conductor 219, demodulator DEM, conductors 216 and 217, filter FR, conductor 215, switch C1 in position a, conductor 213, coil b of transformer M7, conductor 214 and switch C3 in position a. 45 It will be observed that the circuit arrangement for each communication station is normally for receiving messages. Also, forming a part of each communication set is a transmitter or other form of modulator TR of carrier current, an amplifier and generator of carrier current AM and a filter FT in a circuit adapted to be connected to coil b of transformer M7, the circuit including conductors 214 and 207 and conductors 213 and 212, which may be connected by switch 50 C1 in position b, conductors 208 and 211 connecting the filter FT with the amplifier and generator AM and conductors 209 and 210 connecting the transmitter TR with the generator and amplifier AM. The frequency of the carrier current used is high enough so that sufficient energy will be transmitted across the air gaps between the train carried circuits and the intermediate circuit for efficient and satisfactory service; yet, it is low enough so that the amount 55 of energy transmitted to other wayside circuits, than those directly concerned in the communication operation, is so small as to produce little, if any detectable effect in such other circuits. The filters FT and FR are designed to pass 60

electric currents of the desired carrier frequency, but to keep out currents of other frequencies. Means are provided in Fig. 8 for simultaneous listening and transmitting, such as is practiced in commercial telephony. Switch C2 is normally in an open position *a*, but is adapted to be closed in positions *b*, *c*, and *d*. Switch C4 is in a circuit adapted to connect an ear phone EP, or other similar instrument, to the main receiver circuit. Switches C2 and C4 may be combinedly connected to be operated to the various similar positions by the same controlling means. When the switch C5 is moved to the position *d*, the amplifier AQ and the receiver or loud speaker LS are disconnected from the circuit. The resistance connected with switch C4 is adapted to be inserted in the circuit to adjust the intensity of the response to the ear phone. The ear phone EP may be connected through conductor 222 to conductor 218 and through conductor 223, impedance and switch C4 with conductor 218. With this arrangement, the station operator may talk and listen at the same time. If it is desired to leave the loud speaker LS in circuit at the same time the ear phone EP is used, the intensity of the reception in the loud speaker LS may be adjusted by the switch C5 through the impedance connected with it. A switch C3 and adjustable impedance connected therewith is intended for adjusting the intensity of the reception in the loud speaker LS under normal conditions. It may also be used in diminishing the intensity of reception in the ear phones EP. Should amplification be desired for the signals to be received in the ear phones EP, it is obvious amplification may be added to the modulator DEM.

Fig. 9 comprises the same general arrangement of circuits and receiving and transmitting apparatus as Fig. 8, excepting it provides for an audio frequency system instead of a carrier frequency system. The provision for simultaneous transmission and listening is practically identical with the arrangement described in Fig. 8. One difference lies in the switch C8 being arranged only for connecting and disconnecting the loud speaker LS1 from the receiving circuit. TR1 is an audio transmitter or microphone. AM1 is an amplifier for the transmitted current. FT1 is a filter in the transmitting circuit. FR1 is a filter in the receiving circuit. AR1 is a receiving amplifier. Ordinarily, the volume of current in the intermediate circuit, as transmitted from a wayside or train station, is of sufficient intensity to be audible in an ear phone set. However, should this not be the case, amplification for the received signals may be combined in the circuit with filter FR1 if desired. The filters FT1 and FR1 are designed to pass those currents of frequencies within the audio range, which are required for satisfactory service, and to impede current of frequencies outside of the required limits.

Under certain conditions it is desirable to equip local wayside stations, located like Q1 at passing siding location X1 and Q2 at location X2, with communication sets operating on audio frequencies, as illustrated in Fig. 9, or some carrier frequency other than that ordinarily used for the railway communication system in which trains are involved, that communication may be carried on between such stations at the same time that communication is being carried on between the dispatcher and trains and other stations over common circuits. Further, it is obvious that such stations as Q1 and Q2 may be

equipped with two communication sets each, one to operate on a predetermined carrier frequency, the same as that for the trains and the dispatcher, and the other on some other frequency, as the audio frequency. With this arrangement, when communication is desired with the trains, or with the dispatcher, or with the local stations, the conductors 203 and 204 will be connected with the conductors 95 and 96 respectively for local station Q1 and with the conductors 95' 10 and 96' for the local station Q2. When communication between two stations like Q1 and Q2 is desired through the use of the audio frequency set of Fig. 9, conductors 203' and 204' will be connected with the conductors 95 and 15 96 respectively for local station Q1 and with the conductors 95' and 96' for the local station Q2.

Fig. 10 is a cross section of a railway track showing the arrangement of sending and receiving coils or inductors with reference to the two 20 sides of the intermediate circuit for a wayside communication station Q9. This is the arrangement typical for the wayside stations Q3 and Q5 with some modifications for the latter as heretofore explained. For the local wayside stations 25 like Q1 and Q2, the inductors U15 and U17 are not necessary; only inductor U16 would be required connected directly in circuit with the station Q9. As heretofore explained, the stations of which Q9 is representative, may be equipped 30 with communication sets operating on the frequency generally used by the trains; or some, or all of them may be equipped with sets operating upon frequencies distinctively different from that generally used by the trains. In the case 35 of the latter, communication could only be carried on between those stations which are similarly equipped; but such communication could be carried on simultaneously with that being conducted between trains and the dispatcher, 40 the stations of which are operating on a different frequency.

Operation

The communication sets for trains and wayside stations are referred to and described 45 under Figs. 8 and 9.

Figs. 6 and 7, already referred to and described, show the arrangement for co-operation between the train carried communication sets 50 and the wayside or intermediate circuits, in which the co-operation is inductive through an air gap between the wayside circuits and train carried circuits; there are no conductive co-operating features whatever between the train carried 55 circuits and the wayside circuits.

Fig. 10 also heretofore referred to and described, indicates how local wayside stations are arranged in co-operative relation with the wayside circuits.

While this invention is adapted for various kinds of transmitted communications, for convenience I shall hereafter refer to it as a telephone system in which speech is transmitted from one communication station to another.

Assume that a train is in the block comprising section A of Fig. 1, but not in the circuit for track relay TA, the train being equipped with transmitting and receiving telephone communication sets in the caboose and in the locomotive. The intermediate circuit for this block has been heretofore described and designated as Circuit #1. Conversation may be carried on between the caboose and the locomotive via Circuit #1 while the train is within this block.

The normal condition of the circuits and apparatus for each communicating set is as indicated in Fig. 8. Assume that the conductor is to talk to the engineman. He will operate switch C1 to the position *b*, thus connecting transmitter TR with the coil *b* of transformer M7, the coil *a* of this transformer being connected to the train carried inductors such as U9, U10, and U11 of Fig. 7. The conductor talks into the transmitter TR. The speech current developed modulates the carrier frequency and is amplified. The filter FT is designed to check the flow of current of other than the specified frequency; it passes the amplified modulated carrier frequency current which flows through the transformer M7 and the inductors, causing a corresponding magnetic field for each coil or inductor U9, U11, and U10 which field intersects the track rails A1 and A2 and the conductor 1, respectively, causing a corresponding current to flow in the Circuit #1 heretofore described, of which the track rails and conductor 1 are a part. At the locomotive the train carried coils or inductors such as U12, U14, and U13 of Fig. 7 intersect the magnetic field caused by the current flowing in the track rails A1 and A2 and the conductor 1; thus a corresponding current is induced in the circuit of these inductors and flows through the transformer M1, the filter FR, which checks the flow of electric current of frequencies other than the carrier frequency, the demodulator DEM and the amplifier AQ to the loud speaker LS where the voice currents are reproduced as speech. As soon as the conductor has finished talking, switch C1 of his set is restored to its normal position *a*. The engineman may change the switch C1 of his communication set to position *b* and reply to the conductor, the procedure in the operation being similar to that explained in the case of the conductor transmitting.

Should it be desirable for the engineman and the conductor to transmit and hear at the same time, the switch C2 for each communicating set will be operated connecting conductor 212 with conductor 215 and switch C5 may be operated to position *d*, thus disconnecting the amplifier AQ and the loud speaker LS from the circuit. Coincidentally, with the operation of the switch C2 to the desired position, switch C4 may be operated to adjust the resistance or impedance in the circuit of the ear receiver EP so that the volume of sound received is of the proper intensity. With this arrangement, each party in talking may instantly break in on the other. Because of the necessity to get above train noises, the volume of sound given out by the loud speaker LS is far too great for reception in the usual ear phone. Therefore, the adjustable resistance of switch C4 is necessary. However, I may use an amplifier along with the demodulator, and adjust the volume of the output of same, in any case where the communication currents from a remote transmitting station received by the inductors of the train are not of sufficient volume to be clearly and distinctly heard in the ear phones.

The switch C5 is provided not alone for opening the loud speaker circuit in case the output of the loud speaker should be found objectionable when receiving is desired through the ear phones. This switch C5 is also provided with adjustable resistance or impedance to change the volume of the reception in the loud speaker LS should this, at any time be desirable, whether

the ear phones are being used or not. Switch C3 is provided for a purpose similar to that of switches C4 and C5. At the switch C3 the resistance is normally out of the circuit, but it may be inserted to reduce and adjust the volume of sound reproduced by either the loud speaker or the ear phones or both of them. With this arrangement, it is clear that the system of this invention may be used for simultaneous listening and transmitting.

Since the communication sets in the office of the dispatcher and in the local wayside stations are of the same general character and arrangement as that for the train stations, the procedure by the attendants in these stations in the operation of the communication sets and in telephoning, including simultaneous speaking and listening, is the same as that explained in detail for the conductor and need not be repeated.

Since block A is only partially shown in the diagram, Fig. 1, means for connecting the intermediate circuit for block A with the dispatcher's communication circuit, conductors D1 and D2 are not illustrated. In general, however, this means would be on the order of that illustrated and described for the location at section F, so that conversation may be carried on between the dispatcher and the train; and the general procedure in adapting the circuits for this conversation will be hereinafter described for the condition where the train occupies the stretch E-F and is served by the intermediate circuit for that stretch.

When a train, which is moving toward the right in the diagram, passes into the circuit for relay TA, this relay is deenergized, shifting the contacts 2 and 6 to their back points, so that the intermediate circuits for the block which comprises section A and the stretch which comprises sections B, C, and D are now connected together as one circuit, heretofore referred to and described as Circuit #3. Although the train is moving, it will be observed that as it passes from one block to the one adjoining, the intermediate circuit relation with the train carried inductors is continuously maintained.

It has already been explained that inductor U1 is in inductive relation with conductor 5, and, therefore, with the intermediate circuit for stretch B-C-D, and is connected to the communication set for station Q1. Assuming that the communication set of Q1 is of the same character as that on the trains and in the dispatcher's office, conversation may now be carried on between the train and the local station Q1, the procedure by the attendant in the local station being the same as that heretofore described for the conductor.

When the train passes into section B, track relay TB is de-energized, closing back contact 26. As the train is also in the section A, track relay TA being de-energized, back contact 27 is closed. Since back contacts 26 and 27 are now both closed, relay N1 is energized (Circuit #4) and established in a stick circuit through its contact 31a (Circuit #4d) resulting in the intermediate circuit arrangement heretofore described and referred to as intermediate Circuit #3b. Relay N1 on becoming energized, closes the front contacts 14 and 21, thus connecting the transformer M1 with its secondary *a* in the combined intermediate circuit for the block comprising section A and the stretch B-C-D and its primary *b* to the dispatcher's communicating

- circuit, conductors D1 and D2. This places the train in position to communicate with the dispatcher in his station Q4. The procedure on the part of the dispatcher, in conversation with either the conductor or engineman or both on the train, is the same as that heretofore described for the conductor of the train. The communication impulses in a conversation between the train and the dispatcher pass by way of the combined intermediate Circuit #3b, the transformer M1 and conductors D1 and D2. The conductor and engineman are now in conversational relation each through their respective train carried sets and intermediate Circuit #3b.
- 10 The attendant in the local station Q1 may still carry on conversation with the train and he may now also carry on conversation with the dispatcher, both via the intermediate Circuit #3b. It is also obvious that the conductor and engineman, or either of them, may join in a conversation with both the local station attendant and the dispatcher; in other words, all four parties are now "on the line".
- 15 While the train is in the circuits for the two relays TA and TB, the three caboose station inductors U9, U11, and U10 are in inductive relation with the track rails A1 and A2 and the center-of-track-inductor 1; but since the intermediate circuit for the stretch B—C—D does not include the track rails, only inductor U13 of the locomotive set is active in transmitting and receiving from the intermediate circuit; i. e., inductor U13 is in inductive relation with conductor 5.
- 20 When the train has cleared the circuit for relay TA, this relay becomes energized and contacts 2, 6, and 21 are restored to their normal position, but relay N1 remains energized because of the stick circuit established through its front contact 31a. The intermediate circuit is now confined to the stretch B—C—D and heretofore referred to and described as Circuit #2b. As the track rails are not included in this intermediate circuit the co-operation for communication purposes is between inductors U10 and U13 on the train with the center-of-track-conductors 5 and 7, it being assumed that the train is keeping to the main line. Conversation between the conductor and engineman on the train, the dispatcher and the attendant in the local wayside station, or any two of them, may be continued via the intermediate Circuit #2b. The conversation between the train and the dispatcher having been concluded and the dispatcher not wishing to be bothered with any conversation there may be between the conductor and engineman of the train, or between the train and the local station, may annul the connection of the intermediate Circuit #2b to the conductors D1 and D2 by operating the selector L1 to energize the relay O1 to shift the contacts 23, 12 and 18 to their front contact position, after which he may again operate selector L1 to return the contacts to their normal position. The interval of time elapsing between the breaking of back contact 23 and the making of front contact 23 or vice versa, is sufficient to break the circuit of relay N1 to cause this relay to become de-energized, restoring contacts 31a, 14, 10, and 21 to their normal position and re-establishing intermediate Circuit #2.
- 25 During the time that the train is in the stretch B—C—D, and whether intermediate Circuit #2 or #2b is established, the two train carried sets are in continuous communicative relation with

each other and with the set of local station Q1 so that conversation may be carried on at will between the conductor and engineman or between either or both and the attendant in the local station.

Should the track switch S1 have been operated by the device R1 for the train to take the siding, conversation between the conductor and engineman may be carried on continuously if desired since the intermediate Circuits #3, #3a and 1 #3b, #2, #2a and #2b serve both the main line and the passing siding. Conversation between the dispatcher and the train may be carried on while the train is entering the siding, similarly as has been heretofore explained with the train 11 keeping to the main line. Also, conversation may be a four-party affair by way of the intermediate Circuits #3b, #2b and the Circuit #7a and conductors D1 and D2, between the dispatcher in station Q4, the local station Q1 and 20 the conductor and engineman on the train.

As soon as the rear end of the train which is entering the siding has cleared the circuit for the relay TA, the dispatcher may operate the selector L1 to close the contact 35 to energize the 25 relay O1 in Circuit #5 to shift its contacts 23, 12, and 18 to their front points; thus, through the opening of contact 23, de-energizing relay N1 causing front contacts 31a, 14, and 21 to open and back contact 10 to close. At this point, 30 intermediate Circuit #2a is established; but this may be changed, entirely separating the intermediate circuit from the wayside communication circuit, conductors D1 and D2, by the dispatcher again operating selector L1 causing relay O1 to 35 energize to shift its contacts 23, 12 and 18 to their back points and normal condition.

The dispatcher having annulled the connection of the intermediate Circuit #2b through coils a and b of transformer M1 to the dispatcher's circuit, conductors D1 and D2, heretofore described may establish the intermediate Circuit #2a by the operation of the selector L1 to energize the "off and on" relay O1 in the Circuit #5 to close its contacts 23, 12, and 18 on their front 45 points. This operation closes the front contacts 23, 12, and 18 and connects secondary c of transformer M1 in the intermediate circuit and the primary b to the conductors D1 and D2 (Circuit #7). By this means, the dispatcher may carry 50 on conversation with the conductor or engineman, or both on a train on the main line or on the passing siding track, or with the local station Q1 whether a train is within the stretch B—C—D or not.

55 A train TA4 is shown on the passing siding track at location X1 of Fig. 1. The attendants on the train, which I have assumed to be moving over the railway, may carry on conversation with the attendants on the train TA1 while this latter is in the track circuit section for relay TA of block A via intermediate Circuits #3, #3a or #3b; while in the stretch B—C—D via the intermediate Circuits #2, #2a or 2b; and while in the track circuit section for relay TE 60 via intermediate Circuits #9, #9a, #9b or #9c. Also, under the same conditions, both of these trains, or either of them, may carry on conversation with the local station Q1, and with the dispatcher via intermediate Circuits #3a, #3b, #2a, #2b, #9a, #9b, and #9c.

70 Normally, the station Q1 is not in communicative relation with the dispatcher, but such relationship may be established, initiated by the at- 75

tendant in station Q1, by the closure of the contact of push key P2 which energizes relay N1 in Circuit #4a. This establishes the intermediate Circuit #2b connected via transformer M1 and Circuit #7a to conductors D1 and D2 and thus to dispatcher's communication set in station Q4. The procedure in conversation is the same as heretofore explained. When the conversation is finished, the dispatcher may annul the connection 10 of transformer M1 with conductors D1 and D2 in the same manner as heretofore explained.

A train moving toward the right still in passing from either the main line track or the siding track of the passing siding location X1 enters first the circuit for relay TD, closing back contact 31, and then the circuit for relay TE, thus shifting the contacts 42, 8, and 32 to their back points. With contacts 42 and 8 closed on their back points, the intermediate circuits normally existing for stretches B-C-D and E-F are now combined as one circuit heretofore referred to and described as Circuit #9. Communication between the conductor and engineman of the train and the attendant at station Q1 may be carried on at will and continuously, if desired while the train is making this movement.

Since contacts 31 and 32 are closed, relay N1 is again energized, inserting secondary a of transformer M1 in the combined intermediate Circuit #9, establishing the Circuit #9b, and the primary b is connected across the conductors D1 and D2, as referred to in Circuit #7a. Thus, the circuit system is arranged for the train to initiate communication with the dispatcher for announcing its departure from the passing siding location X1 and for any other communication which may be desired between the dispatcher and the train. During this interval local station Q1 being in communicative relationship through inductor U1 with the combined intermediate Circuit #9b may carry on conversation with the train and with the dispatcher.

As soon as the train has cleared the circuit of relay TD, the dispatcher may then, or thereafter, disconnect the combined intermediate circuit for the stretches B-C-D and E-F (Circuit #9b) or the individual circuit for stretch B-C-D (Circuit #2) from his communication circuit, conductors D1 and D2, by operating the selector L1 and consequently, the relay O1 as heretofore described.

It will be observed that the annulling of the connection established by the relay N1 of the intermediate circuit for stretch B-C-D with the dispatcher's communication circuit, that is, the changing of the intermediate Circuit #2b back to intermediate Circuit #2, cannot be accomplished so long as a train occupies both of the two track circuits for relays TA and TB or both of the two track circuits for relays TD and TE. The dispatcher can annul the connection, after the same has been established, whenever a train traveling in either direction has cleared the insulated joints between the sections A and B and sections D and E.

When the train proceeding toward the right has cleared the track circuit of relay TE, the normal intermediate Circuit #8 for the stretch E-F is restored. Communication between conductor and engineman of the train may be carried on via Circuit #8, in a manner similar to that heretofore described for other blocks. Assume that the dispatcher desires conversation with the train in the stretch E-F. He will operate his selective equipment DSE to send out a

code of impulses over the circuit including conductors D1 and D2 to which selector L2 will respond and none other. This will cause contact 35a to close, energizing "off and on" relay O2 in Circuit #12 to close its contacts 38, 52, and 46 on their front points. The closing of contact 46 connects primary b of transformer M2 via Circuit #14 directly to the dispatcher's communication circuit, conductors D1 and D2. The closing of front contact 38 inserts secondary 10 coil c of transformer M2 in the intermediate circuit for the stretch E-F, establishing Circuit #8a. The closing of front contact 52 inserts the secondary a of transformer M2 in the intermediate circuit for the block G establishing Circuit 15 #10a. It will be noted that with this arrangement, when the dispatcher operates selector L2 he connects the two intermediate circuits, that for stretch E-F (Circuit #8) and that for block G (Circuit #10) to his communication circuit 20 conductors D1 and D2. Conversation between the conductor and engineman of the train and the dispatcher may now be carried on via the communication circuit conductors D1 and D2, transformer M2 and intermediate Circuit #8a. 25 When through with the conversation, the dispatcher may disconnect his communication circuit conductors D1 and D2 from the intermediate Circuits #8a and #10a by the operation of the selector L2 and consequently, relay O2. This 30 re-establishes intermediate Circuit #8 for stretch E-F and intermediate Circuit #10 for block G.

When the train passes into the section F, relay TF is energized, due to the wheels and axles across rails A1 and A2, closing contacts 54, 49, and 51 35 on their front points so that the intermediate circuits for the stretches E-F and G are now combined as one circuit, #11. Conversation between the conductor and engineman of the train may now be carried on via intermediate Circuit 40 #11. Should the dispatcher wish to communicate with the train at this time, he will operate the selector L2 to insert the coils a and c of transformer M2 in the intermediate Circuit #11 and connect coil b to the conductors D1 and D2, 45 as heretofore explained, thus establishing intermediate Circuit #11a. The closing of front contact 51 shunts secondary a of transformer M2 so that only secondary coil c remains in the combined intermediate Circuit #11a, thus lowering 50 the impedance of the circuit. The dispatcher may now carry on conversation with the train through combined intermediate Circuit #11a and primary b of transformer M2. This may be continued as long as the train is within the section 55 F and until the relay O2 is again operated to restore its contacts 38, 52, and 46 to their normal condition. Conversation between the conductor and engineman at this time will be via combined intermediate Circuit #11a. 60

When the train has cleared the track section F, relay TF becomes de-energized and the contacts 54, 49, and 51 are returned to their normal position. The combined Circuit #11a is abolished and Circuit #10a is re-established and 65 now functions for conversation between the conductor and engineman, and between the dispatcher and the train, since the contacts 38, 52, and 46 still remain on their front points. Should the dispatcher cancel the connection of the intermediate circuit for block G with his communication circuit, conductors D1 and D2, by the operation of selector L2, contact 52 would be made on its back point, thus re-establishing intermediate Circuit #10. Conversation be- 70 75 75

tween the conductor and engineman of the train would now be through this circuit.

The train continues into the circuit of relay TG, de-energizing this relay and causing contacts 56, 60, and 81 to be made on their back points, thus connecting together as one combined Circuit #17 the normal circuits for block G and stretch H—I—J. During the period that the train is in the circuit for relay TG, conversation may be carried on between the conductor and engineman via Circuit #17.

Should the dispatcher desire to communicate with the train while it occupies the track circuit for relay TG, he will operate selector L3 to establish Circuit #17a connected to his wayside communication circuit, conductors D1 and D2. Conversation between the conductor and engineman and the dispatcher will now be by way of intermediate Circuit #17a, transformer M3 and wayside communication circuit, conductors D1 and D2. When the conversation is concluded, the dispatcher may disconnect combined intermediate Circuit #17a for block G and stretch H—I—J from conductors D1 and D2 by the operation of selector L3 to restore contact 66 to its back point, thus re-establishing intermediate Circuit #17.

It should be noted here that the dispatcher may also carry on conversation with the train while it is in the track circuit for relay TG, by closing the contacts 52 and 46 of relay O2 on their front points by the operation of selector L2, thus establishing intermediate Circuit #17c.

While the train is in the section for relay TG, conversation may be carried on between the train and the local station Q2 via the combined intermediate Circuits #17, #17a, #17b or #17c and U2. When the train enters the circuit for relay TH, but is still in the circuit for relay TG, back contacts 80 and 81 are closed, energizing relay N2 in the Circuits #18 and #19 to close its contacts 85a, 68, and 75 on their front points and to break the contact 64 from its back point. This automatically connects the confined intermediate circuit for block G and stretch H—I—J, Circuit #17b, with the dispatcher's communicating circuit, conductors D1 and D2, via primary b and secondary a of transformer M3. The train attendants are now in position to announce to the dispatcher the arrival of the train at passing siding location X2, and conversation between the train attendants and dispatcher may be carried on. Also, the train attendants may have conversation with the local station Q2, and this latter with the dispatcher.

As the train clears the circuit for relay TG, this relay becomes energized, restoring the individual intermediate circuits for block G and stretch H—I—J, #10 and #16. The train conductor and engineman may still carry on conversation between themselves and with the dispatcher and with the local station Q2 and the latter and the dispatcher may talk together.

The dispatcher may now annul the connection of the intermediate Circuit #16 for the stretch H—I—J, with his communicating circuit conductors D1 and D2 by operating selective equipment DSE to send out the code of current impulses to which selector L3 will respond, closing its contact 89. This energizes relay O3 to shift its contacts 77, 66, and 72 to their front point; thus relay N2 is de-energized and coils a and b of transformer M3 are disconnected from the intermediate Circuit #16 for stretch H—I—J and from the communicating circuit conductors D1

and D2 respectively. However, when relay O3 is energized to shift its contacts to their front points, coil b of transformer M3 is connected to conductors D1 and D2 through contact 72 and coil c of transformer M3 is inserted in circuit 5 with intermediate Circuit #15, establishing intermediate Circuit #15a, so that conversation between the train stations, the dispatcher and the train and the local station Q2 may be continued. But, if selector L3 is again operated to 10 energize relay O3, contacts 77, 66 and 72 are shifted to their normal condition, back points; primary b of transformer M3 is disconnected from the conductors D1 and D2 and secondary coil c is shifted out of the intermediate circuit 15 for H—I—J. Intermediate Circuit #15 is re-established for stretch H—I—J. Conversation may still be continued between the conductor and engineman on the train and between either or both of them on the train and the local station Q2. The procedure in carrying on conversation between the conductor and engineman on the train and between the local station Q2 and the train attendants when at passing siding location X2 is similar to that already described 20 for the passing siding location X1. Also, the operation of the circuits for the various positions of the train for conversation with the dispatcher is similar to that described for passing siding location X1.

Intermediate circuit #24 for the block K has been heretofore described. Within this block is a local wayside station Q3 associated with the intermediate Circuit #24 through coils a and c of inductor set U3 being in inductive relation 35 with track rails A1 and A2 respectively and coil b being in inductive relation with conductor 94. Local station Q3 is always in communicative relation with a train in block K, and with the train when it approaches or leaves block K so 40 that the intermediate circuit for block K is combined with the intermediate circuit for the adjoining stretch as the stretch H—I—J. The intermediate circuit for the stretch H—I—J combined with the intermediate circuit for the 45 block K is Circuit #24a heretofore described. Assuming that the block K is provided with a circuit organization the same as that controlled by the selector L2, the dispatcher may confer with the attendant in the local station Q3 by 50 operating the selector to connect the intermediate Circuit #24 or an enlarged intermediate circuit as #24a with the communication circuit conductors D1 and D2. It is also obvious that when the train is in the track circuit section 55 for relay TK, that communication between the dispatcher and the attendant in station Q3 may be carried on by way of the intermediate Circuit #24a, transformer M3 and conductors D1 and D2.

Let it be assumed that two wayside local stations, for example, local stations Q1 and Q2 are each equipped with a communication set operating on a frequency different from that used on the trains and in the dispatcher's office, 65 and that these two local stations desire to converse at the same time that the conductor and engineman of train TA2 wish to talk with each other. Push keys P2 and P5 of stations Q1 and Q2, respectively, are operated to connect the 70 intermediate Circuits #2 and #15, for stretches B—C—D and H—I—J, respectively, through the respective transformers M1 and M3 with the wayside communication circuit conductors D1 and D2. Conversations may now be carried on 75

at the same time, in a manner as heretofore described, between the attendants at the stations Q_1 and Q_2 and between the conductor and engineman of train TA_2 . As the communication signals are carried on different frequencies, there will be no interference of one set of conversations with the other. It is also evident, that at the same time that conversation is under way between the attendants of stations Q_1 and Q_2 , the dispatcher may talk with train TA_2 , or TA_1 or TA_4 ; or he may operate the selector L_2 controlling transformer M_2 and talk to trains TA_3 and TA_5 coincidentally with the attendants in local stations Q_1 and Q_2 talking with each other. In each of the examples mentioned, a plurality of conversations may be transmitted simultaneously over circuits which are common to both sets of communications. The stations Q_1 and Q_2 may be equipped with a plurality of communication sets, one set on a frequency for communication with the trains and the dispatcher and the other set on a different frequency for communication between the attendants in the two stations. Simultaneous speaking and listening may be indulged in, for the stations concerned with each set of communications, in a manner heretofore explained.

I have shown two trains passing each other at location X_1 . Train TA_4 is on the passing siding track and train TA_1 is on the main line track. These trains may communicate with each other and the local station Q_1 via the intermediate Circuit #2. The dispatcher may have conversation with the local station Q_1 and either or both trains by way of intermediate Circuit #2a, transformer M_1 and conductors D_1 and D_2 .

Other than the trains TA_4 and TA_1 in stretch $B-C-D$, I have shown train TA_3 in stretch $E-F$, train TA_5 in block G and train TA_2 in block X_2 . Since the intermediate circuits for these blocks are electrically isolated from each other, communication cannot normally be carried on between the trains, except trains TA_1 and TA_4 . Excepting for the last two mentioned trains, conversations may be carried on simultaneously between the conductor and engineman on each train, without the conversation for any one train being heard by, or interfering with the conversation of, any other train. Train TA_2 may have conversation with local station Q_2 and normally, this conversation will be exclusive to the train and station Q_2 and independent of that with and on other trains.

The dispatcher, after operating the selector associated with any intermediate circuit, may have conversation with any communication station associated with that circuit; for example, by operating the selector L_1 , the dispatcher may have conversation with any one or all of the stations on trains TA_1 and TA_4 and with local station Q_1 , and this conversation is exclusive to the stations mentioned. Similarly, the dispatcher may have conversation with trains TA_3 and TA_5 through the coils a and c respectively of the transformer M_2 , and this conversation will be exclusive to the two trains and the dispatcher. Other communication stations, where two or more are associated with the same intermediate circuit, may carry on communication between themselves at the same time the dispatcher is talking with trains TA_3 and TA_4 . Other examples may be cited, as is evident, to show the flexibility and high degree of utility of the system embodied in this invention.

75 Referring to the method of connecting the

intermediate circuits with the dispatcher's communication circuit, conductors D_1 and D_2 , as illustrated for stretch $E-F$ and block G , it is evident that by omitting the coil a of transformer M_2 and the connections thereto through the contact 52 of relay O_2 , that only the intermediate circuit for stretch $E-F$ will be connected to the conductors D_1 and D_2 when selector L_2 is operated. Such a circuit organization may also be provided for the block G , in which event the dispatcher may have exclusive conversation with either train TA_3 or TA_5 . I have illustrated the method for connecting the two intermediate circuits for stretch $E-F$ and block G to the conductors D_1 and D_2 at the same time primarily for the reasons of economy, and convenience for the dispatcher. For railway lines of light and moderate traffic, and especially single track lines, there would seldom be more than one train between passing siding locations X_1 and X_2 at any one time.

It is obvious I have provided a communication system in which each train is normally in a communication zone of its own, which, in effect, travels with the train and to which communications of the train are restricted. In it are incorporated provisions harmonizing with the general method of operating trains on a modern railway.

In the operation of trains over the railway line equipped as indicated in Fig. 3, both sides of the intermediate circuits are in inductive relation with the inductors on the train and the inductors for the local wayside station, the track rails connected in parallel forming one side of the intermediate circuit and the conductor in the center of the track, the other side of the intermediate circuit.

With a train in the track circuit for relay T_5 , the relay contacts 182 and 105 are made on their back points, thus establishing the intermediate Circuit #30. Electric current impulses for conversation between the conductor in the caboose and the engineman in the cab of the locomotive are transmitted through intermediate Circuit #30. Also, voice currents passing between a train station and the local wayside station Q_5 flow in intermediate Circuit #30 and through inductor U_5 . Should the dispatcher desire conversation with the train at this time, he will operate selector L_5 to cause the closing of front contacts 115 and 159 , thus establishing intermediate Circuit #30 in circuit relationship with conductors D_1 and D_2 through the coils b and c of transformer M_5 . Over this channel conversation may be carried on between the conductor and engineman of the train, the attendant in local wayside station Q_5 and the dispatcher.

When the train enters section N , relay T_6 de-energizes closing contact 130 , thus energizing relay N_4 in Circuit #31 to close front contacts 131 , 154 and 156 on their front points to connect coils a and b of transformer M_5 in intermediate Circuit #30 and to conductors D_1 and D_2 respectively. Back contact 113 being opened when relay N_4 is energized, coil c of transformer M_5 , if still in Circuit #30, is eliminated from the circuit. The conductor and engineman on the train may talk to each other and may initiate and carry on conversation with the dispatcher. Station Q_5 , being inductively connected to intermediate Circuit #30, may have conversation with both the train attendants and the dispatcher.

When the train clears track circuit section of relay T_5 , intermediate Circuit #30 is automati-

cally replaced by intermediate Circuit #26b through which conversation between conductor and engineman, attendant at local station Q5 and dispatcher may be carried on.

- 5 Assuming that the track switch S5 is reversed so that the train passes into the passing siding PS, intermediate Circuit #26b is replaced by intermediate circuit #28a through which conversation between conductor and engineman on 10 the train, the wayside station Q5 and the dispatcher may be maintained. Communicative connection of station Q5 may now be through either inductor set U4 or U5.

When the train enters the track circuit of 15 relay T1, back contact 141 is closed, energizing relay N3 so that intermediate Circuit #28a is replaced by intermediate Circuit #28c.

When train clears the circuit of relay T6 which is when it passes over the insulated joints separating track circuit for relay T6 from relay T7, dispatcher, by operating selector L5, causes relay O5 to change its contacts to their front contact position and then to their back contact position, thus de-energizing relay N4 and disconnecting coils a and b of transformer M5 from the intermediate Circuit #28c and from the conductors D1 and D2. This establishes intermediate Circuit #28b. Conversation may be carried on between the conductor and engineman 30 on the train, and between the conductor, engineman, local station Q5 and the dispatcher while the train is in communicative relation with intermediate Circuits #28c and #28b.

When the train clears the track circuit of relay T7, dispatcher may change the intermediate Circuit #28b by operating the selector L4 to de-energize the relay N3. Thus, through the opening of contacts 163 and 166 of relay N3, transformer M4 is disconnected from the intermediate circuit and from the conductors D1 and D2 and intermediate Circuit #28 is established. Conversation between the conductor and engineman on the train and the local wayside station Q5 through either inductor set U4 or U5 may be

45 carried on via Circuit #28 as desired. Assume that at this time there is a second train on the main line in the section O, the two trains may communicate with each other and with the local wayside station Q5 via the Circuit #28. The train is now in the section O of the siding track and the switch S5 is still reversed. If the dispatcher wishes to communicate with the train, he operates the selector L4 to energize the relay O4 to close the contacts 145, 125, and 169 on

50 their front points. This inserts coil a of transformer M4 in intermediate Circuit #28 and coil b is connected across the conductors D1 and D2. The conductor and engineman may still talk with each other and the attendant in local station Q5, and the dispatcher may talk with any one or all three. When through with the conversation, the dispatcher operates the selector L4 to re-establish intermediate Circuit #28. When switch S5 is returned to its normal position, Circuit #28 is abolished and normal intermediate circuits, #26 for the main line track and #27 for the passing siding track are re-established.

Communication may be carried on between the conductor and engineman on the train on 70 the siding in section O through intermediate Circuit #27. There may also be communication between the local station and train via inductor set U4 and intermediate Circuit #27.

The conductor and engineman on a train on 75 the main line in section O may communicate

with each other and with the local station Q5 through intermediate Circuit #26, inductor set U5 being in inductive relation with the track rails A1 and A2 and conductor 108.

Intermediate Circuits #26 and #27 are normally electrically isolated from each other; therefore, a train on the passing siding track and another train on the main line track are not normally in communicative relation with each other.

The dispatcher may have telephone conversation with a train on the passing siding in section O by operating the selector L4 to connect the coil a of transformer M4 in the intermediate Circuit #27, thus establishing the intermediate Circuit 15 #27a, and to connect the coil b through front contact 169 with the wayside communication circuit conductors D1 and D2. Similarly, he may have conversation with a train on the main line in section O by operating the selector L5 to connect the coil c of the transformer M5 in the intermediate Circuit #26, thus establishing the intermediate Circuit #26a, and to connect the coil b through front contact 159 with the wayside communication circuit conductors D1 and D2. The 20 dispatcher may also have conversation with local station Q5 through either intermediate Circuit #27a or #26a. Also, the local station Q5 may have conversation through inductor set U4 with a train on the passing siding and through inductor set U5 with a train on the main line. Inductor set U4 is in inductive relation with both sides of intermediate Circuit #27 or #27a, and inductor set U5 is in inductive relation with both sides of intermediate Circuit #26 or #26a. The 35 dispatcher may, at any time, annul the connection of transformer M4 with intermediate Circuit #27a and transformer M5 with intermediate Circuit #26a by operating the selectors L4 and L5 respectively.

A train on the main line track and a train on the siding track may have communication with each other through two sets of connections:

(a) The train on the main line in proceeding into the section O has operated controlling relay 45 N4 to automatically connect intermediate Circuit #26b with the dispatcher's communicating circuit, conductors D1 and D2, by way of transformer M5 and Circuit #35a.

(b) The train on the siding in proceeding into 50 section O has operated controlling relay N3 to automatically connect intermediate Circuit #27b with the dispatcher's communicating circuit, conductors D1 and D2, by way of transformer M4 and Circuit #38a.

With the connections via (a) and (b) established, it is obvious that conversation can be held between the train on the main line and the train in the siding via the channel, intermediate Circuit #26b, transformer M5, the conductors D1 and D2, transformer M4 and the intermediate Circuit #27b.

Should the connections of the intermediate circuits as made through the operation of the 65 relays N3 and N4 have been annulled by the dispatcher, communication between the train on the siding and the train on the main line, both in the section O, may be established through operation by the dispatcher of selectors L4 and L5, 70 thus creating intermediate Circuits #27a and #26a and Circuits #38 and #35 respectively for the siding and the main line. This channel of communication for the two trains is via intermediate Circuit #27a, the transformer M4, con- 75

ductors D1 and D2, transformer M5 and intermediate Circuit #26a.

It is also obvious that inductor sets U4 and U5 may be placed in circuit in series by the operation of a switch at station Q5, which would disconnect the communication set of Q5, connect coil c of set U4 with coil a of set U5 and connect conductors 184 and 135 together. This channel for communication between the trains on the siding and on the main line would be independent 10 of the dispatcher's circuit, conductors D1 and D2, and would include the intermediate Circuit #27, the inductor set U4, the inductor set U5 and the intermediate Circuit #26.

Assume a train on the main line in section O, all circuits being normal, proceeding into the circuit of relay T9, de-energizing this relay. Back contact 139 is closed, energizing relay N4 to close the front contacts 137, 154, and 156 and 20 open the back contact 113. This automatically establishes intermediate Circuit #26b connected via coil b of transformer M5 through front contact 156 with conductors D1 and D2. The conductor and engineman on the train may now 25 converse with the dispatcher and with the local station Q5. The conductor, engineman, dispatcher and attendant in local station Q5, or any two of them, may talk together.

The train proceeds into the track circuit of 30 relay T10 which becomes de-energized, making contacts 180 and 111 on their back points so that the enlarged or combined intermediate Circuit #40b is established. Front contact 156 being closed, intermediate Circuit #40b is connected to the dispatcher's circuit, conductors D1 and D2, through transformer M5 by Circuit #35a. Conversation may be carried on between the conductor and engineman on the train, the attendant at station Q5 and the dispatcher 40 while the train occupies the track circuit sections for relays T9 and T10.

As the train moves along to clear the track circuit for relay T9, the dispatcher may annul 45 the connection of the intermediate Circuit #40b by operating the selector L5 to cause de-energization of relay N4 and consequently the opening of front contacts 137, 154, and 156 and the closing of back contact 113. The intermediate Circuit #40 is now re-established and the conductor and engineman on the train and the attendant in station Q5 may converse with each other.

Should the dispatcher wish to talk to the conductor and engineman on the train and the 55 attendant in local station Q5, he may do so by the operation of selector L5 causing front contacts 115 and 159 to be made on their front points, thus establishing Circuit #40a connected to conductors D1 and D2 by Circuit #35. When 60 the conversation is concluded, the dispatcher will usually again operate selector L5 to disconnect the intermediate circuit from the conductors D1 and D2, thus re-establishing the intermediate Circuit #40.

After the train clears the track circuit for 65 relay T10, the normal intermediate Circuit #26 for the main line in stretch N—O—P and #39 for the main line in block Q are re-established. The conductor and engineman on the train may 70 converse as desired while the train is in block Q. The dispatcher may have conversation with the conductor and engineman by operating the selector, not shown, for block Q connecting the intermediate Circuit #39 to the communication circuit, conductors D1 and D2. The procedure

in establishing communication for block Q is the same as heretofore described for stretch E—F.

When a train on the passing siding PS in block O moves into the circuit for relay T8, contact 152, on closing, energizes relay N3, establishing intermediate Circuit #27b connected to the dispatcher's communication circuit, conductors D1 and D2 by Circuit #38a. The conductor or engineman on the train may initiate 10 conversation with the dispatcher in which all four parties, the conductor, engineman, attendant in local station Q5, and dispatcher, may engage, each party being able to talk with any other party and hearing what the other parties, 15 when such are talking, have to say.

Switch S6 must be reversed for the train to proceed to and on the main line. The reversal of this switch establishes intermediate Circuit #29b. The conductor and engineman on the 20 train, the attendant in station Q5, and the dispatcher may communicate with each other via the Circuit #29b, any party talking to any one 25 of the other parties and the remaining parties being able to listen to what is being said. 25

When the train proceeds to the switch S6, relay T9 is de-energized, closing back contact 139, and, consequently, energizing relay N4. Relay N4, when energized, establishes intermediate Circuit #29c, by inserting coil a of transformer M5 in intermediate Circuit #29b and connecting coil b to conductors D1 and D2. As will be noted by reference to Circuit #29c, the intermediate circuit is now connected to the dispatcher's communicating circuit conductors 35 D1 and D2 through both transformers M4 and M5. The conductor and engineman on the train, the attendant in the local station Q5, and the dispatcher in his office may all communicate together, each hearing what is said when any one 40 party talks.

The train moves on toward the right with its front end in the track circuit for relay T10 and its rear end still on the siding. The de-energizing of relay T10 shifts contacts 180 and 111 to their back points, thus connecting the intermediate Circuit #39 for the block Q with the intermediate Circuit #29c for the main line and passing siding in stretch N—O—P and establishing intermediate Circuit #42c. Conversation may be carried on between the conductor and engineman on the train, the attendant in local station Q5 and the dispatcher in his office, any two or all the parties being able to talk together as may be desired. 55

When the train clears the circuit for relay T8, the dispatcher may disconnect the transformer M4 from both the intermediate circuit and his communication circuit by the operation 60 of the selector L4 in the manner heretofore explained. This would establish the intermediate Circuit #42b through which communication between the train attendants, the attendant in local station Q5 and the dispatcher may 65 be continued.

When the train, still moving toward the right, clears the circuit for relay T9, the dispatcher may disconnect the transformer M5 from both the intermediate circuit and his communication circuit by the operation of the selector L5. 70 This establishes the intermediate Circuit #42. Also track switch S6 may be restored to its normal position; this would result in establishing intermediate Circuit #40. The conductor and engineman on the train may carry on conversa- 75

tion between them and they may also have conversation with the attendant in local station Q5. Should the dispatcher wish to again communicate with the train, he may do so by operating the selector L5, energizing relay O5 to close the contacts 115 and 159 on their front points. This connects the intermediate circuit with the conductors D1 and D2 through transformer M5, establishing Circuit #40a. Dispatcher may now talk with the conductor and engineman on the train and with the attendant in the local station Q5. When the conversation is concluded, the dispatcher again operates the selector L5 energizing relay O5 to close the contacts 115 on its back point and open contact 159. This disconnects the transformer M5 from both the intermediate circuit and the conductors D1 and D2, thus restoring intermediate Circuit #40. The conductor and engineman on the train and the attendant in local station Q5 or any two of them may talk together while the train is associated with the intermediate Circuits #40a and #40.

When the train, still moving toward the right, clears the circuit for relay T10, this relay energizes closing contacts 180 and 111 on their front points. This restores the normal intermediate Circuits #26 and #39 for stretches N—O—P and Q respectively. While in the block Q conversation may be carried on between the conductor and engineman of the train but not directly with the attendant of station Q5. The train stations may be placed in communicative relation with the station Q by the dispatcher operating the selector L4 or L5 for stretch N—O—P and the selector for the block Q. This would place the intermediate Circuits #26 and #39 in electrical relation with the conductors D1 and D2, so that communication between the train attendants and the local station Q could be carried on by this channel. Should the dispatcher desire communication with the train, he would connect the intermediate Circuit #39 with the conductors D1 and D2 by the operation of the selector (not shown) for the block Q.

In Fig. 3, as well as in Figs. 1 and 2, when a train passes from one block to an adjoining block and the intermediate circuits which are normal to each block, are temporarily joined together as one circuit, the conductors forming the sides of each intermediate circuit are connected in transposed relation. These transpositions may not be necessary in some locations; but in other locations, where there are foreign current influences, the transpositions serve to minimize any inductive effect there may be from such foreign current.

In Figs. 1 and 2 the closing of the circuits of the relays N automatically by a train through the contacts of adjoining relays is for the purpose of reducing to a minimum the time interval within which the energizing of the relays N is influenced by the train. It will be observed in these figures that the relays N are influenced to be energized by the train only during the interval that the train is passing a given point, which point is at the insulated joints separating the adjoining track circuits; for example, the point where the track circuits for relays TD and TE abut. In Fig. 3 I have shown the relays N energized in a circuit influenced to be closed by one track circuit relay as, for example, relay T6. This relay influences the closing of the circuit for relay N4 during the entire time a train is within its track circuit. However, in practice

the section of track for such track circuits is usually short.

The push keys P6 and P7 may be located at any convenient place. They are preferably placed at the station Q5. Should the attendant on a train on either the main line or passing siding in station O desire to initiate communication with the dispatcher, it will only be necessary for him to telephone the attendant in local station Q5 to close either key P6 or P7, depending upon which track the train is on.

Having described my invention, what I consider new and desire to have protected by Letters Patent will be pointed out in the appended claims.

What I claim as new is:

1. In a communication system for railways, a stretch of railway including a main line track and a siding track connected with said main line track by switches, a train in said stretch, a wayside station, a first intermediate circuit for the main line track, a second intermediate circuit for the siding track, a wayside communication circuit connected with the wayside station, locally controlled means associated with each of the intermediate circuits for connecting said circuits with the wayside communication circuit, and other means associated with each of said circuits and controlled from said wayside station for annulling said connection.

2. In a communication system for railways, a stretch of railway track for trains, a plurality of passing siding locations in said stretch, an intermediate circuit at each location associated with both the main line track and the passing siding track at said location, a telephone transmitting and receiving set at each location, a circuit for each set connected in inductive relation with the intermediate circuit at the corresponding location, a dispatcher's office, a wayside communication circuit connecting with the dispatcher's office, a transmitting and receiving telephone set in the dispatcher's office connected with the wayside communication circuit, a circuit switch associated with each passing siding location suitable for controlling the connection of the intermediate circuit for the corresponding location with the wayside communication circuit, and circuit controlling means in the dispatcher's office effective to disconnect and reconnect said wayside communication circuit from any one, or more than one, of said intermediate circuits, said connection and disconnection being effective whether said stretch is occupied by a train or unoccupied.

3. In a communication system for railways, a stretch of railway track for trains, a plurality of intermediate circuits in said stretch associated with said track, a plurality of wayside telephone sets each individually associated with a different intermediate circuit, normally open control circuits substantially coextensive with said different intermediate circuits, a wayside line, a circuit closing contact associated with each telephone set for closing the associated control circuit, and a switching device operated in response to said circuit closure for controlling the connection of its associated intermediate circuit with said wayside line.

4. In a communication system for railways, a stretch of track and a train therein, a communication circuit associated with said stretch, communication apparatus on said train inductively associated with said circuit, a wayside station, a communication circuit extending to said station,

means controlled by said train approaching a particular point in said stretch for automatically connecting said two circuits, means controlled from said station for terminating said connection, and means controlled by said train for rendering said last means ineffective until the train has passed said particular point.

5. In a communication system for railways, a stretch of railway including a passing siding location, a main line track and a passing siding track at said location, an intermediate circuit associated with both of said tracks, a train in said stretch, a wayside communication circuit, and means controlled by said train automatically connecting the said intermediate circuit with the wayside communication circuit as the train approaches said location and again as the train leaves said location.

6. In a communication system for railways, a stretch of railway including a passing siding location, a main line track and a passing siding track at said location, a track switch in the main line track adapted when reversed to connect the main line track with the passing siding track, an intermediate circuit for the main line track, an intermediate circuit for the passing siding track, said circuits being each normally closed and electrically isolated from each other, a circuit controlling switch associated with said track switch effective when said track switch is reversed to connect said intermediate circuits together as one circuit, a wayside communication circuit, a train in said stretch, and means controlled by the train as it approaches said passing siding location connecting said one circuit with said communication circuit.

7. In a communication system for railways, a stretch of railway including a passing siding location, a main line track and a passing siding track at said location, a track switch in the main line track adapted when reversed to connect the main line track with the passing siding track, an intermediate circuit for the main line track, an intermediate circuit for the passing siding track, said circuits being each normally closed and electrically isolated from each other, a circuit controlling switch associated with said track switch effective when said track switch is reversed to connect said intermediate circuits together as one circuit, a train in said stretch, a wayside communication circuit for said stretch, a dispatcher's station connected with said wayside communication circuit, means controlled by the train connecting said one circuit with said communication circuit, and means at passing siding location controlled from the dispatcher's station adapted to connect said one circuit to and disconnect said one circuit from said wayside communication circuit, said last means functioning to cancel the connection of said one circuit with the wayside communication circuit as established by said train controlled means.

8. In a communication system for railroads, a railway line comprising two tracks connected by a track switch, a separate closed loop circuit for each track, remotely controlled means for inductively connecting said loop circuits, and track switch controlled means for conductively connecting said loop circuits.

9. In a communication system for railways, a railway line including a main track and a siding track, a train operating on said railway line, a track switch adapted to be reversed to connect said siding track with said main track, an in-

termediate circuit for each track adapted to receive communications from and transmit communications to trains operating on the associated track, means controlled by said track switch when set to permit the train to enter said passing siding track for communicatively connecting said intermediate circuits, and means controlled by the train occupying said siding track to maintain a connection between said circuits after said track switch is returned to its normal position.

10. In a communication system for railroads, a railway line comprising a main line track and a siding track, a track switch at each end of said siding track connecting the siding track with the main line track, an intermediate circuit for that portion of each track included between the track switches, said circuits being normally closed metallic loops electrically separated from each other, a wayside station, means controlled from said wayside station for communicatively connecting said two intermediate circuits, and circuit connecting means associated with each track switch, adapted to be operated when said switch is reversed to also communicatively connect said two intermediate circuits.

11. In a communication system for railways, a railway line including two tracks connected at two different points by track switches, a separate closed loop circuit for each track, means responsive to the operation of one of said track switches for joining the two loop circuits as one large loop circuit, and means responsive to the operation of the other track switch for separating said large loop circuit into two separate loop circuits.

12. In a communication system for railways, a railway line including two tracks connected at two different points by track switches, a separate closed loop circuit individual to each track, means responsive to the operation of one track switch for joining said loop circuits as one large loop circuit common to both tracks, and means responsive to the operation of the other track switch for separating said large loop circuit into two separate loop circuits, both of which are common to both tracks.

13. In a communication system for railways, a railway line including two tracks connected at two different points by track switches, a separate closed loop for each track, each of said loops comprising the rails of the associated track and a return conductor, means responsive to the operation of one of said track switches for joining said loop circuits to form a single large loop circuit comprising the rails of both tracks and said return conductors connected in series, and means responsive to the operation of the other track switch for separating said large loop circuits into two loop circuits, one of which comprises the rails of both tracks and the other of which comprises said return conductors.

14. In a communication system for railways, a stretch of railway including a passing siding location, a main line track and a passing siding track at said location, a track switch in the main line track adapted when reversed to connect the main line track with the passing siding track, a train on the siding track, another train on the main track, and a communication set for each end of each train comprising a telephone transmitter, a telephone receiver and a coil in circuit with the transmitter and receiver located near to but separated by an air gap from each of the track rails upon which the train operates, the arrangement being such that the track rails

in parallel carry the transmitted telephone currents between the ends of each train, said currents originating on each train being exclusive to said train, except when said track switch is 5 reversed.

15. In a communication system for railways, a stretch of railway including a passing siding location, a wayside station, a main line track and a passing siding track at said location, an 10 intermediate circuit associated with each of said tracks, a train in said stretch, a wayside communication circuit, means controlled by said train for automatically connecting the intermediate circuit with the wayside circuit as the train approaches 15 said location, means controlled from the wayside station for cancelling said connection after the train has moved to within the limits of said passing siding track, and means controlled by the train for automatically re- 20 establishing said connection as the train leaves said location.

16. In a system of communication for railways, a stretch of railway including a main track and a siding track, said siding track being connected to the main track by switches at each end thereof, a loop circuit individual to the main track, a loop circuit individual to the siding track, each of said circuits being associated with that portion of its respective track lying 30 between said switches, and means operative with either switch in open position to join said two loop circuits together to form one loop circuit.

17. In a communication system for railway trains, a stretch of railway track, a train in said 35 stretch, a transmitting set and a receiving set at each end of the train, a closed circuit for said stretch located upon said track and comprising the two running rails of the track and a conductor connected to the rails at a point a distance ahead of the train and at a point a distance behind the train, the location of said points changing in accordance with the movement of the train, and a circuit at each train end connected with the respective transmitting and receiving sets and in direct inductive relation with the running rails and with said conductor.

18. In a communication system for railways, a stretch of railway including a main line track and a siding track, a track switch in said stretch connecting the siding track with the main track, a closed loop circuit for each track, said loop 5 circuits being normally entirely separate from each other, a wayside communication circuit, a wayside station connected with said wayside circuit, means controlled by a train in passing over said track switch from the main line track to 10 the siding track for connecting each of said loop circuits with the wayside circuit, and means controlled from the station at will for disconnecting either or both of the loop circuits from the wayside circuit. 15

19. In a communication system for railways, in combination, a stretch of track containing a passing siding location, a main line track and a passing siding track at said location, a train on the main line track, a train on the passing siding track, a wayside station, transmitting and receiving communication sets on each of said trains and at said station, means controlled by the train on the main line track for establishing communicative relation between the communication set on that train and the set at the wayside station, and means controlled from said station for establishing communicative relation between the communication set at the station and the set on the train on the passing siding track, the 30 sets on said trains being thereby placed in communicative relation with each other.

20. In a communication system for railways, in combination, a stretch of railway track for a train, a plurality of intermediate circuits in said 35 stretch associated with said track, a plurality of local wayside telephone sets each inductively associated with a different intermediate circuit, a wayside line, a circuit closing contact associated with each telephone set for effecting the 40 connection of the associated intermediate circuit to said line, a dispatcher's station connected with said line, and means controlled from said station over said line for interrupting any connection to the line established by a local station. 45

ARCHIBALD G. SHAVER.
